CODED TRACK CIRCUIT SIGNALING
SYSTEM

Neil D. Preston, Rochester, N. Y., assignor to General Railway Signal Company, Rochester, N. Y.

Application September 30, 1941, Serial No. 413,021

52 Claims. (Cl. 246—33)

The present invention relates to automatic signaling systems for railroads, and more particularly to the application of direct current coded track circuits to the control of wayside signals for a single track railroad for providing protection for both opposing and following train movements substantially equivalent to a line wire absolute-permissive-block signaling system.

The conventional coded track circuit provides that "impulses" of current are successively applied to one end of a track circuit section with spaced intervals conveniently termed "off" periods to comprise a "driven code," the impulses of which are applied at selected rates in accordance with traffic conditions of an adjacent track circuit section. At the opposite end of the track circuit section, suitable code responsive means is employed to receive the driven code impulses and decode such impulses in accordance with their rate for distinctively controlling the indication of a signal governing traffic into that track circuit section without the use of any line wires.

In my prior application, Ser. No. 365,065, filed November 9, 1940, a coded track circuit is disclosed in which an "inverse code" is transmitted in a direction opposite to the driven code by impressing impulses upon the track circuit during the "off" periods of the driven code at the end of the track circuit section which is receiving the driven code. Then suitable means is employed to receive the "inverse code" impulses at the end of the track circuit section sending the driven code. In my above-mentioned application, I disclose means for checking or insuring the integrity of the inverse code receiving means, and the system of the present invention applies the principles of such a checked coded track circuit to an A. P. B. signaling system. However, it is to be understood that no claim is made herein to any subject matter disclosed in such above mentioned prior application.

In the system of the present invention, the coding apparatus for all of the track circuit sections is normally in operation and organized so that the head-block signals at any given passing siding are normally clear to permit trains to leave that passing siding in either direction.

One of the objects of the present invention is to provide that the prevailing direction of driven code in the track circuit sections at the opposite ends of a stretch of single track shall be toward their respective head-block signals to not only provide that the head-block signals shall be normally clear, as above mentioned, but also to facilitate in the provision of double distant cau-

tion control and the overlap siding control usually provided in A. P. B. systems. The system of the present invention also contemplates that any intermediate track circuit section in a stretch of single track shall have its normal driven code in a predetermined prevailing direction; and that the prevailing direction of the driven code in the siding section of track shall also be for a predetermined selected direction.

10 Another object of the present invention is to provide novel means for reversing the prevailing direction of driven code in the track sections as required to clear signals for train movements, but at the same time to facilitate the restoration 15 of the direction of driven code to the prevailing direction after the passage of a train in a manner to eliminate prolonged code flights.

In an A. P. B. system, it is necessary to provide what has been conveniently termed a tumble- 20 down circuit organization which acts when a train enters a stretch of single track to place all opposing signals of the stretch at stop. With such an arrangement, it is necessary to provide what is commonly known as a directional stick 25 relay associated with each of the intermediate signals to so act on the tumble-down circuits as to permit following train movements with the usual block spacing.

Thus, another object of the present invention 30 is to provide a novel control for directional stick relays for use in coded track circuit A. P. B. signaling systems. This novel control is of the so-called straddle-joint type, that is, a train must pass from one track section into another over the 35 intervening insulated joints in order to pick up the directional stick relay for the corresponding direction of travel.

This is accomplished in the present invention by including in the pick-up circuit for a given 40 directional stick relay a back contact of the decoding means for the track section in approach to a signal in addition to a front contact of a series track relay for the track section in advance of that signal with means for allowing such pick- 45 up circuit to be closed only momentarily after the train passes the signal. Such an organization assures that a train must actually be present on a track section and travelling in a direction corresponding to the direction of traffic governed by 50 the signal which it is passing.

Other objects, purposes, and characteristic features of the present invention will be in part obvious from the accompanying drawings and in part pointed out as the description of the invention progresses.

In describing the invention in detail, reference will be made to the accompanying drawings in which like letter reference characters provided with distinctive numerals designate corresponding parts through out the several views, and in which;

Figs. 1A, 1B, 1C and 1D, when placed end to end, illustrate an A. P. B. signal system organized in accordance with the present invention.

Fig. 2 illustrates a diagram of the normal conditions of the system.

Figs. 3A to 3F illustrate diagrams of the different conditions of the system for east-bound train movements.

Figs. 4A to 4F illustrate diagrams of the different conditions of the system for west-bound train movements.

Figs. 5A to 5F illustrate diagrams of the different conditions of the system for east-bound following train movements.

Figs. 6A to 6F illustrate diagrams of the different conditions of the system for west-bound following train movements.

Figs. 7A to 7F illustrate diagrams of the different conditions of the system for two opposing train movements for a meet at a passing siding.

For the purpose of simplifying the illustration and facilitating in the explanation, the various parts and circuits constituting the embodiment of the invention have been shown diagrammatically and certain conventional illustrations have been employed, the drawings having been made more with the purpose of making it easy to understand the principles and mode of operation than with the idea of illustrating the specific construction and arrangement of parts that would be employed in practice. Thus, the various relays and their contacts are illustrated in a conventional manner, and symbols are used to indicate connections to the terminals of batteries, or other sources of electric current, instead of showing all of the wiring connections to these terminals.

The symbols plus (+) and minus (-) are employed to indicate the positive and negative terminals respectively of suitable batteries or other suitable sources of direct current; and the circuits with which these symbols are used always have current flowing in the same direction.

Referring to Figs. 1A, 1B, 1C and 1D when placed end to end, it will be seen that a stretch of single track is shown extending between the head-blocks of two passing sidings with the apparatus at such head-blocks so organized that the positioning of duplicates of Figs. 1A, 1B, 1C and 1D to the right of Fig. 1D (or to the left of Fig. 1A, as the case may be) illustrates the circuit organization required for the control past the siding as contemplated in accordance with the present invention. This has been illustrated in the traffic movement diagrams of Figs. 2, 3, 4, 5, 6 and 7. It will thus be seen that by reproducing the figures of the present disclosure and selecting their relative positions to each other, the signaling system required for the various track layouts afforded by a single track railroad will be completely disclosed.

Referring to Figs. 1A, 1B, 1C and 1D a stretch of single track between two passing sidings of a single track railroad has been illustrated. This stretch of single track has signals 1 to 8, inclusive, for governing traffic thereover in opposite directions, and for the purposes of the present disclosure they have been shown to be of

the color-light type with suitable marker lamps to indicate the absolute or stop-and-stay signals when the marker is in vertical alignment with the main signal, but to indicate a permissive or stop-and-proceed signal when the marker lamp is off-set from the main signal. Although color-light type signals have been illustrated, it is to be understood that many other types, such as search-light signals, position light signals, and the like, might well be employed, the color-light type of signal being selected as a convenient means for illustrating the different signal indications given under the various conditions of traffic.

With reference to Fig. 2, which illustrates diagrammatically the normal conditions of the system, it will be seen that the portion of the railway shown in Figs. 1A to 1D inclusive has been assumed to be re-produced and placed to the right of Fig. 1D so as to illustrate a stretch of single track between passing sidings A and B, and another stretch of single track between passing sidings B and C.

In these diagrammatic illustrations of the condition of the system under varying traffic movements, symbols have been used to indicate the controlled conditions of the various signals, and the signal arms of such symbols have been shown "heavy" for those signals which are illuminated. In other words, the usual symbol with the light line semaphore arm indicates the controlled condition of a signal without the illumination of its lamps; while the symbol having the heavy line signal arm indicates not only the controlled condition of the signal but also that its lamps are illuminated.

It is noted that the even numbered signals are for governing east-bound traffic, while the odd numbered signals are for governing west-bound traffic (see Figs. 1A, 1B, 1C and 1D). Also, the track section between any two opposing signals has been given a reference character corresponding to those signals, as for example, the section of track between signals 2 and 3 has been designated track section 2-3T, so as to readily identify the various adjoining track sections which are, of course, suitably insulated from one another.

Each signal location has its associated apparatus which is quite similar to the apparatus associated with every other signal with a few exceptions. These similar devices have been given the same letter reference characters which are made distinctive by reason of the preceding numerals which correspond with the number of the signal with which they are associated. Thus, the apparatus may be described in general with reference to such apparatus by the letter reference characters instead of specifying the particular signal location with which such device is associated.

It is assumed that the coded track circuit is of the conventional direct current type, using primary batteries, or trickle-charge storage batteries as a source for the track circuit current, but it should be understood that the same principles may be applied to coded track circuits energized from alternating current sources.

It is also contemplated that the transmitted driven codes are of specified distinctive rates, such as 75, 120 and 180 "on" and "off" periods per minute, although any other suitable rates might be employed. These different rate codes are produced from suitable code generating devices such as code oscillators in accordance with

the usual practice, the contacts of such oscillators being illustrated diagrammatically as C15, C120 or C180, as the case may be. For the purpose of this disclosure, the code oscillator contacts C15, C120 and C180 are assumed to be on separate oscillators for the different rates, all of which are normally operating at their respective rates; and each signal location is provided with oscillators individual to that location as required for the different codes transmitted from that location. It is to be understood that such oscillators may have starting and stopping means employed so as to cause their operation only when any particular oscillator is required to supply a code. It is also to be understood that various kinds of code generators or oscillators may be employed, and that a single motor might drive coding contacts for all three different rates if desired.

For the purpose of illustrating the codes employed under varying traffic conditions, an arrow with a solid line shaft is used to designate the direction and presence of a driven code, while an arrow with a dotted line shaft is used to indicate the presence and direction of an inverse code. Also, the numbers 75, 120 or 180 appearing closely adjacent these arrows indicate the rate of the code represented by such arrow. The arrows of Figs. 1A, 1B, 1C and 1D show the codes normally appearing in the various track sections with the prevailing directions, of course, indicated. The same conditions are also illustrated in Fig. 2 where the two stretches of single track have been shown, thus giving a more complete picture of the signaling conditions associated with the opposite ends of a passing siding.

In the track circuit sections at the opposite ends of a stretch of single track adjacent the head-block signals, the prevailing direction of the driven code is toward the head-block signals and the direction of the inverse code must, therefore, be away from the head-block signals. In the intermediate track circuit sections, such as section 4-5T, the direction of driven code under normal conditions could be in either direction but for convenience in the illustration the prevailing direction has been shown as being from right to left. The same thing is true with regard to the siding track circuit section 8-1T where the normal prevailing direction of driven code could be predetermined for either direction but for the purpose of the disclosure has been assumed to be from right to left.

The various codes are supplied to the track circuits by code transmitting relays CP which are two-position polar type relays. The contacts of each of these code transmitting relays CP are normally biased to one position to connect the associated track relay TR across the track rails and are effective when in the opposite or operated position to connect the associated battery in series with the associated series track relay SR across the track rails. The track relays TR are also of the two-position polar type having their contacts biased to a particular position, while the series track relays SR are of the neutral type with suitable operating margins to allow the usual coding current to be applied to the track circuit without picking up. However, when a train is present in the associated track circuit section and the series relay SR with its associated battery is connected across the track rails, the series relay SR then picks up. Although the track circuits might be organized so that the entrance of a train into any given track circuit section would

cause the immediate picking up of the series relay SR at the distant end of that section, it is contemplated in accordance with this invention that the series relay will not pick up until the train is approximately half way through a track circuit section. This arrangement assures a more positive action of the series relay, especially on the drop away when a train leaves the section.

Each track relay TR has associated therewith a neutral track repeating relay TP which is energized upon each energization of its associated track relay TR. It should also be noted in this connection that the track relays TR respond both to the driven codes and to the inverse codes, the distinction between the different codes being made in the control circuits.

The code transmitting group of apparatus also includes a code sending relay CS at certain locations, such as the head-block signal locations and those intermediate signal locations which are at the receiving end of the normal driven code of an intermediate track circuit section.

One of the significant features characteristic of this invention is that the control circuits for the code transmitter relays CP include back contacts of their respective track relays TR. Thus, any given code sending relay CP cannot be energized to transmit the next impulse of a driven code until its associated track relay TR has been released after responding to the impulse of an inverse code. This checks the reliability of the reception of an "off" or "inverse" code as will be explained more in detail hereinafter.

Associated with each signal location that must transmit an "off" code or an "inverse" code is an "off" code transformer TF which is energized upon each energization of its associated track relay TR and is deenergized when such associated track relay is released. The energization of the transformer TF, of course, induces a current in its secondary winding which flows through the associated transmitter relay CP over the inverse code controlling circuit, but this current flow is of such a direction as to fail to actuate the contacts 35 of the polar relay CP to operated positions. On the other hand, the current induced in the secondary of this "off" code transformer TF when the associated track relay TR is deenergized, is of a proper direction and intensity to momentarily 40 actuate the associated code sending relay CP. In this way, an "off" code or "inverse" code pulse is momentarily placed upon the track rails between any two successive impulses of a driven code, such inverse code of course being applied 45 only under the proper traffic conditions as will be explained later. However, it should be pointed out that this method of providing an inverse code may be varied so as to use battery energy through suitable circuit control means without the inductive transformer arrangement and still be within 50 the scope of the present invention.

The decoding apparatus at each signal location includes two decoding transformers TFA and TFB; a home relay H; and distant relay D. The home relays H are of the neutral type and are connected to the first decoding transformer TFA in such a way as to be responsive to any code received over the track rails above a given rate, that is, each home relay H responds to all of the code rates 75, 120 and 180. These home relays H are designed so as to remain picked up when receiving pulses for even the slow 75 code rate, but to drop away immediately upon the cessation of any of the codes. The distant relay D is connected through a rectifier arrangement, a trans-

former TFB, and a condenser to the first transformer TFA in such a way as to form a resonated circuit combination responsive only to the 180 code rate. At certain signal locations, such as at signal 8 of Fig. 1D, a distant relay DX is connected through a transformer TFC and rectifier arrangement so as to be responsive only to the 120 code rate.

Certain of the home relays H have associated therewith slow-acting repeater relays HP which directly repeat the picked up and dropped away condition of their respective home relays H with predetermined time intervals of delay.

Each signal, except the signals governing traffic into a siding section, has an associated directional stick relay S which is picked up by the passage of a train past that signal in the direction which it governs.

It is believed that further characteristics of the system will be best understood by considering its operation for certain typical traffic conditions.

OPERATION

General.—It is believed expedient before considering in detail the circuit organization, to briefly outline the mode of operation of the system as to the codes employed for the communication of signal control conditions through the various track circuit sections with more particular consideration of the direction of code transmission under certain traffic conditions. Such traffic conditions and codes are illustrated in the diagrams of Figs. 2 through 7 to which reference will be made as the description progresses.

With reference to Fig. 2, the normal conditions of the system are illustrated in which the control apparatus for each of the signals is conditioned for the clear indication of such signal, although only the leaving signals, such, for example, as signals 2 and 7, actually display clear indications, while the other signals are normally dark. In other words, all of the signals are approach lighted except the leaving or head-block signals which are continuously illuminated.

A 180 driven code is normally transmitted through each of the track sections. The direction of driven code transmission for each siding section is normally from right to left, while the direction of driven code transmission for each of the end sections of each stretch of single track between sidings is normally toward the adjacent siding. The prevailing direction of driven code transmission for the intermediate track sections of each stretch of single track between sidings has been shown to correspond with that for the siding sections for the sake of uniformity, but it should be understood that the opposite direction of prevailing driven code may be selected for either section. It will also be noted from Fig. 2 that the driven code of each track section has an associated inverse code transmitted in a direction opposite to the normal direction of such driven code.

Although it appears from Fig. 2, that signals are controlled to clear conditions by inverse codes, the system is so organized that a train proceeds for usual train movements in accordance with signals cleared by driven codes. When a train approaches a track section in which the normal direction of driven code corresponds with the direction of the train, means is provided to automatically reverse the direction of the driven code from its normal direction so that it will be transmitted toward the train to clear the signal at the entrance to such section.

This feature will be better understood by reference to Fig. 3B, where the train of Fig. 3A has moved into the track section 2—3T, which causes the direction of driven code to be reversed in the track section 6—7T so as to cause the signal 6 to be cleared by a driven code. Incidentally, the entrance of the train into the track section 2—3T causes the approach lighting of both the signals 4 and 6.

10 It is desirable to clear signals for usual train movements by driven codes, because there are a greater number of distinctive driven codes than there are inverse codes available for controlling any given signal in accordance with the various traffic conditions.

15 As mentioned above, the prevailing direction of the driven codes in the end track sections of each stretch of single track is toward the adjacent siding, which facilitates the provision of single block siding over-lap control for the signals governing entrance to the siding track sections. This feature of over-lap control will be discussed later in connection with the diagrams of Fig. 7.

20 Fig. 3A is the first in a series of figures illustrating the conditions of the system upon passage of an eastbound train when the trackway is assumed to be unoccupied for a considerable distance in advance of such train. The presence of the east-bound train in the siding section 8—1T of siding A, as illustrated in Fig. 3A, is effective to cause a restrictive indication to be displayed by the opposing signal 2, but signal 3 is not caused to display a caution indication unless an opposing train is in approach to signal 3 to cause the reversal in the direction of driven code transmission in the end track section 2—3T adjacent the siding A. Conditions involving opposing trains will be hereinafter discussed.

25 Considering the progress of the east-bound train as illustrated in Fig. 3B, the entrance of the train into the stretch of track between the sidings A and B causes the dropping away of the H relays for the signals 3 and 5 by removing the inverse code which is normally transmitted for their energization. The dropping away of such relays of course causes the signals 3 and 5 to be conditioned for the display of stop indications, but such indications are not displayed because the approach lighting is not effective under these conditions. The removal of the inverse code transmitted from left to right through track section 4—5T for the control of signal 5 causes the driven code transmitter for the left-hand end of the track section 6—7T to become inactive for the transmission of a driven code, and such inactivity is effective to cause the reversal in the direction of driven code transmission in the track section 6—7T. With the reversal in the direction of driven code transmission in that track section 6—7T, the code transmitter at the left-hand end thereof becomes active for the transmission of an inverse code from left to right through such track section, but the reception of such inverse code at the right-hand end of the track section cannot be effective to clear the signal 7 although it does cause the relay H for that end of the track section to be energized. The signal 7 is held at stop under such conditions because of the energized condition of the relay 7CS for that end of the track section 6—7T, which relay 7CS is picked up upon the shifting in the direction of driven code transmission through the track section. It is by this mode of operation that train detection is effective for the track section 6—7T for east-bound trains while at the same time

maintaining the entering signal 7 at stop in accordance with the general principles of absolute-permissive-block signaling systems.

The putting to stop of signal 7 cancels the inverse code transmitted from left to right through the siding track section 8-1T of siding B, and conditions the apparatus at the right-hand end of the siding B so that the signal 1 is controlled to stop, although the signal is maintained dark. This condition, however, would not exist if there were a west-bound train in approach to the signal 1 on track section 2-3T, as the approach of such train would cause the reversal in the direction of driven code transmission through the siding section 8-1T, and the reversal of the direction of code transmission in that section would cause the signal 1 to be put to caution if the overlap section 6-7T were unoccupied by the east-bound train as illustrated in Fig. 3B. The mode of operation under conditions where opposing trains are involved will be more readily understood hereinafter when reference is made to the conditions illustrated in Figs. 7A through 7F.

When the siding track section for the siding A becomes unoccupied in the rear of the east-bound train, the conditions of driven and inverse code transmission are restored except that a 120 driven code is transmitted rather than a 180 code as selected by the east stick relay for signal 2. The 120 code causes the conditioning of the entering signal at the opposite end of the siding to indicate caution, but such signal is dark unless it is being approached by a train. The 120 code in the siding section of course provides that the D relay for the control of signal 1 cannot be picked up, and therefore such signal is put to caution. The caution indication of signal 1 provides for a back up move of the east-bound train. The conditions are different for the control of signal 1 for a back up move from the control of such signal for a usual west-bound train movement as will be apparent as the description progresses.

As the east-bound train proceeds further along the trackway as illustrated in Fig. 3C so as to occupy the track section 4-5T, it will be noted that the advance of the train to such track section has no material affect upon the conditions of code transmission in advance of the train. When the track section 2-3T in the rear of the train becomes unoccupied, the normal direction of driven code transmission is restored for that track section, and the signal 2 for governing entrance to that block is properly put to caution in accordance with the 75 driven code transmitted through such track section. This condition of code transmission is of course selected in accordance with the picking up of the east stick relay for the signal 4.

The advance of an east-bound train into the track section 6-7T as illustrated in Fig. 3D does not alter the conditions of code transmission for the track sections in advance of the train if no opposing train is present. However, it will be readily apparent that the entrance of the east-bound train into the track section 6-7T renders the transmission of the inverse code through such track section ineffective, and therefore causes the dropping away of the 7H relay at the right-hand end of that track section. The dropping away of such relay 7H so conditions the code transmitter for the left-hand end of track section 8-1T that such transmitter will be rendered inactive if an opposing train is immediate-

ly in approach of the entering signal 1. Such condition is illustrated in Fig. 7D. When the track section 4-5T becomes unoccupied in the rear of the east-bound train, restoration becomes effective similar to that described for the track section 2-3T when it became unoccupied by the train, a 75 driven code being transmitted from right to left through the track section 4-5T for governing the caution indication of signal 4. The picking up of the 4H relay at the left-hand end of track section 4-5T under such conditions changes the code transmitted from right to left through the track section 2-3T to complete the restoration to normal of the conditions of code transmission for such track section. The transmission of an inverse code from left to right through the track section 4-5T under the conditions illustrated in Fig. 3D causes the signal 5 to be put to caution in accordance with the 75 code transmitted through that track section. This is, of course, in accordance with the deenergized condition of the relay 5D for such signal.

When the east-bound train advances into the siding section 8-1T of siding B, as illustrated in Fig. 3E, it will be noted that the normal conditions of code transmission for the track sections in advance of the train are maintained. When the track section 6-7T becomes unoccupied in the rear of the train, there is a temporary code fight between the driven code transmitters for the opposite ends of such track section as illustrated by the direction arrows of Fig. 3D, but the arrangement of the circuits is such that the code transmitter for the left-hand end of the track section overrules the code transmitter for the right-hand end thereof so as to restore the normal direction of driven code transmission through the track section. A 180 driven code is transmitted in the section 6-7T under such conditions depending upon the reception of the inverse code at the right-hand end of the adjacent track section 4-5T. The reception of the 180 driven code at the right-hand end of track section 6-7T causes the clearing of signal 7 and causes the transmission of an inverse code from right to left through the track section in accordance with the normal conditions as illustrated in Fig. 2. The reception of the inverse code at the left-hand end of track section 6-7T causes the 75 driven code formerly transmitted through the track section 4-5T to be changed to a 180 driven code, and thus to complete the restoration to normal of the conditions for the stretch of single track between the sidings A and B.

The advance of the east-bound train from the siding section 8-1T for the siding B into the track section 2-3T, as illustrated in Fig. 3F, causes conditions to be established in advance and in the rear of the train corresponding to those which have been considered with reference to a similar traffic condition illustrated in Fig. 3B. It will be noted upon comparing Figs. 3E and 3F with specific reference to the direction of driven code transmission in the siding section 8-1T, that a code fight occurs between the transmitters for the opposite ends of such track section when it becomes unoccupied by a train. However, the apparatus of the system is so organized as to cause the direction of driven code transmission to be established from right to left in accordance with the predetermined prevailing direction of the driven code.

After having considered the general mode of operation of the system upon passage of an east-bound train through a typical portion of track-

way, it will be readily apparent with reference to Figs. 4A through 4F that the mode of operation upon the passage of a west-bound train is somewhat similar, although it is necessarily modified to some extent because of the necessity for reversing the direction of driven code transmission upon the approach of a west-bound train to a siding section, such as track section 8-1T, and upon the approach of a west-bound train to an intermediate track section such, for example, as the track section 4-5T.

With reference to Fig. 4A, when a west-bound train enters the stretch of track between the sidings B and C, the direction of driven code transmission is reversed for the end track section 2-3T by a mode of operation similar to that which has been described under similar circumstances for the entrance of an east-bound train into a stretch of single track between sidings. The condition is different for the intermediate track section 4-5T, however, in that the driven code normally transmitted from right to left through such track section is removed when the tumble-down becomes effective for such stretch of track, and the removal of such code renders the code transmitter for the left-hand end of that track section effective for the transmission of a driven code from left to right for the control of signal 5. The 180 driven code is transmitted through such track section 4-5T dependent upon the energized condition of the relay 3H for the right-hand end of the adjacent track section 2-3T.

The conditions of code transmission for the track section in the rear of the west-bound train in Fig. 4A are restored to normal in a manner generally similar to that described in connection with Fig. 3B for the restoration to normal of the codes transmitted for an east-bound train. The putting to stop of the opposing entering signal 2 upon the tumble-down when the west-bound train enters the stretch of single track between sidings B and C, causes the code in the siding sections 8-1T for the siding B to be changed from a 180 code to a 75 code. Such change is, of course, effective to cause the relay 8D for the left-hand end of the siding B track section to be dropped away, and thus condition the control apparatus for signal 8 so that such signal would display caution upon the approach of an east-bound train.

Upon comparing the conditions of code transmission through the siding section for the siding B of Figs. 3F and 4A, it will be noted that under the conditions of Fig. 3F, the code transmitted is a 120 code, and under the conditions of Fig. 4A, the code transmitted is a 75 code. The reception at the left-hand end of the track section 8-1T of the 120 code causes the energization of a relay 8DX by a tuned circuit, and the energization of such relay is effective to cause the intermediate signal 6 in the rear of the entering signal 8 to be cleared if there is a west-bound train in approach to such signal. However, if a west-bound train is in approach to the signal 6 when a 75 driven code is transmitted through the siding section 8-1T, the signal 6 is put to caution because of the transmission of a 75 code through the track section 6-7T as selected by the de-energized condition of the relay 8DX for the left-hand end of the siding section 8-1T. Although such conditions are not particularly obvious from the diagrams which have been considered, they are more readily apparent under traffic conditions involving opposing train movements shown

in Figs. 7A through 7F and discussed in detail hereinafter. But it is believed sufficient at this point in the description to understand that by this mode of operation, a single caution indication is provided for following trains, and a double caution indication is provided for opposing trains in accordance with the desired practice in absolute-permissive-block signaling systems.

The advance of the west-bound train into the track section 4-5T so as to cause the track section 6-7T to become unoccupied in the rear of the train as illustrated in Fig. 4B allows the restoration of driven and inverse code transmission through the section 6-7T in a manner very similar to that heretofore described when considering the passage of an east-bound train as illustrated in Fig. 3C.

When the intermediate track section 4-5T becomes unoccupied in the rear of the west-bound train, a code fight is effective for such track section as illustrated by the arrows representing the direction of driven code transmission in Fig. 4C, and the code transmitter for the right-hand end of the track section is effective to over-rule the transmitter at the opposite end to establish the normal direction of driven code transmission. The conditions illustrated in Fig. 4C for track section 4-5T are therefore only momentary, as the solving of the code fight is effective to establish the conditions for the track section 4-5T as illustrated in Fig. 4D. The reception of the driven code at the left-hand end of the track section 4-5T causes the transmission of an inverse code to the right to give clear conditions to the apparatus for signal 5, but the lamps of signal 5 remain dark. On the other hand, if a following west-bound train were to approach signal 5, the 180 driven code and the inverse code shown would be cut off by such following train while the energization of the west-bound stick relay for signal 3 would be effective to cause a 75 driven code to be transmitted from left to right to control signal 5 to display a caution indication as will be described in connection with Fig. 6A.

The advance of the west-bound train into the section 8-1T associated with the siding B as illustrated in Fig. 4E causes restoration to become effective for the track sections in the rear of the train in the manner similar to the mode of operation which has been described when considering the passage of an east-bound train.

When the siding section 8-1T becomes unoccupied in the rear of the east-bound train as illustrated in Fig. 4F, the solving of a code fight for the transmitters for the opposite ends of that track section in favor of the driven code transmitter for the right-hand end of the track section allows restoration to the normal conditions of the system for code transmission through that track section. Although the apparatus for the control of signal 1 is conditioned for the clearing of such signal in accordance with the normal conditions of the system, the reversal in the direction of driven code transmission through the siding section 8-1T upon the approach of signal 1 by a following west-bound train would be effective in accordance with the energized condition of the west-bound stick relay for signal 7 to cause a 75 driven code to be transmitted from left to right for the caution indication of signal 1. This condition is illustrated in Fig. 6D.

Having thus described the general mode of operation of the system upon the passage of re-

spective east and west-bound trains, it is believed that the mode of operation for other traffic conditions, as illustrated in Figs. 5, 6 and 7, will be readily understood as the description progresses.

Normal conditions

With reference to Figs. 1A, 1B, 1C and 1D placed end-to-end in that order, it will be noted that the system is normally in operation so that the apparatus at each of the signal locations is in operation to normally produce codes as indicated by the arrows shown in Fig. 2 adjacent the track. Thus, the decoding relays H and D associated with the various signal locations are normally energized in accordance with the normally transmitted codes so as to normally clear the signals, all of which has been explained in general in connection with the conditions described with respect to the diagram of Fig. 2.

Inasmuch as the apparatus at each of the various signal locations is similar in its organization, and the interconnecting track circuits are also similar, it is believed that the detailed consideration of the operation of the apparatus associated with one particularly track circuit section will be sufficient for an understanding of the operation of the apparatus associated with the other track circuit sections. There are, of course, certain exceptions to this general similarity, as for example, the control of the code transmitter relays CP, which control will be discussed in detail with respect to each of such relays.

As a specific example of the normal conditions of code communication through a track section, the conditions will be described in detail relative to the end track section 2-3T (see Figs. 1A and 1B). The code transmitter relay 3CP (see Fig. 1B) is normally active for the transmission of a 180 driven code because of its energization for each impulse of the oscillator C180. The circuit by which relay 3CP is energized for each impulse of oscillator C180 extends from (+), including contact 29 of relay 3TR in its left-hand position, contact 21 of oscillator C180, front contact 22 of relay 4H, and winding of relay 3CP, to (-).

During each pulse of relay 3CP the contact 23 is actuated to its left-hand position, and in that position it closes the track circuit for track section 2-3T for the transmission of a driven code impulse. The track circuit is closed under such conditions from the positive terminal of track battery 24 including contact 23 of relay 3CP in its left-hand position, lower rail of track section 2-3T, contact 25 of relay 2CP (see Fig. 1A) in its left-hand position, winding of relay 2TR, upper rail of track section 2-3T, and winding of the series relay 3SR (see Fig. 1B), to the negative terminal of track battery 24. The energization of that track circuit for each pulse of the code transmitter relay 3CP is effective to cause the contact of relay 2TR to be actuated to its right-hand position, but the series relay 3SR of course does not respond, as the characteristics of such relay are marginal in that the series relay is active only when the track section is shunted by a train relatively close to the signal location with which such series relay is associated.

For each pulse of the track relay 2TR (see Fig. 1A), the relay 2TP is picked up by the energization of an obvious circuit closed at contact 26 of relay 2TR in its left-hand position. The picking up of the relay 2TP for each pulse received closes an obvious circuit at front contact 75

- 27 for the upper portion of the primary winding of transformer 2TFA. The closing of back contact 27 of relay 2TP at the end of each impulse of the code received closes a circuit for the lower portion of the primary winding of transformer 2TFA to cause a reversal in the direction of energization as compared to the energization of the upper portion of the winding in accordance with the closure of front contact 27.
- 10 In accordance with the reversal in the direction of energization of the primary winding of the transformer 2TFA responsive to the pulsing of contact 27 of relay 2TP, the relay 2H is normally maintained energized by the alternating current set up in the secondary winding 28 of transformer 2TFA as rectified by the contact 29 of relay 2TP. That is, the shifting of contact 27 of relay 2TP in synchronism with contact 29 causes the secondary winding 28 of transformer 2TFA to have its upper and lower portions alternately connected to the relay 2H so as to cause such relay to be energized by pulsating direct current.
- 15 An alternating current is also set up in the secondary winding 30 of transformer 2TFA when a code is being received at the left-hand end of track section 2-3T, and the alternating current thus set up flows through a tuned circuit including the primary winding 31 of transformer 2TFB.
- 20 The secondary winding 32 of the transformer 2TFB is connected across a full-wave rectifier 33 which provides for the feeding of direct current to the relay 2D in an obvious manner. The tuned circuit for the primary winding of the transformer 2TFB is tuned so as to cause sufficient current to flow for the picking up of the relay 2D only when a 180 code is being received at that end of the track section 2-3T.
- 25 Each H relay has a repeater relay HP which is normally energized. For example, the relay 2HP is normally energized by an obvious circuit closed at front contact 34. The circuit for the control of relay 2HP is typical of the circuit provided for the control of each of the other relays HP.
- 30 In accordance with the energized condition of the relays 2H and 2D, the leaving signal 2 for the siding B normally displays a clear indication because of the energization of the green lamp of such signal by a circuit closed from (+), including back contact 35 of relay 2CS, front contact 36 of relay 2H, front contact 37 of relay 2D, and the green lamp G of signal 2, to (-).
- 35 The transformer 2TF has its primary winding energized for each impulse received at the left-hand end of track section 2-3T by the energization of an obvious circuit closed at contact 38 of relay 2TR in its left-hand position. Upon the opening of such contact at the end of each impulse received under normal conditions, the collapse of the flux in the transformer 2TF causes an induced voltage in the secondary winding of the transformer to be effective to pick up the code transmitter relay 2CP for the transmission of an impulse of an inverse code. The relay 2CP is energized under such conditions by a circuit extending from the left-hand terminal of the secondary winding of the transformer 2TF including front contact 39 of relay 2H, back contact 40 of relay 2CS, and winding of relay 2CP, to (-).
- 40 The relay 2CP is of course only momentarily picked up as its energization is terminated when the collapse of the flux of the transformer 2TF has become complete. Due to the polar characteristics of the relay 2CP, it is not responsive to the flow of current through its
- 45
- 50
- 55
- 60
- 65
- 70

winding upon the building up of the flux in the transformer 2TF.

The picking up of the relay 2CP for the transmission of an impulse of an inverse code causes the picking up of the track relay 3TR (see Fig. 1B) at the right-hand end of the track section 2-3T by the energization of a circuit extending from the positive terminal of track battery 41 (see Fig. 1A) including contact 25 of relay 2CP in its right-hand position, lower rail of track section 2-3T, contact 23 of relay 3CP (see Fig. 1B) in its right-hand position, winding of relay 3TR, upper rail of track section 2-3T, and winding of the series relay 2SR (see Fig. 1A), to the negative terminal of track battery 41.

At the right-hand end of track section 2-3T, the relay 3TP (see Fig. 1B) follows the inverse code received in accordance with the pulsing of contact 42 of relay 3TR, and the pulsing of contacts 43 and 44 of relay 3TP causes the relays 3H and 3D to be picked up by the energization of circuits which correspond with those that have been specifically described for the energization of the relays 2H and 2D for the left-hand end of the track section. The energized condition of the relays 3H and 3D is not effective, however, to cause the signal 3 to display a clear indication, as the circuits for the lamps of such signal are open at back contact 45 of relay 4HP.

The code transmitter relay 1CP (see Fig. 1A) for the right-hand end of the track section 8-1T is normally active for the transmission of a 180 driven code from right to left through that track section because of the energization for each impulse of the oscillator C180 of a circuit extending from (+), including contact 46 of relay 1TR in its left-hand position, contact 47 of oscillator C180, back contact 48 of relay 2CS, front contact 49 of relay 2HP, normally closed contact 50 of the switch circuit controller for the track switch 1W, and winding of relay 1CP, to (-). The pulsing of contact 51 of relay 1CP is effective to cause the transmission of a driven code by the energization of a track circuit similar to that described for the track section 2-3T except that such track circuit does not include a series relay SR. To consider the manner in which the driven code transmitted from the right-hand end of the siding section 8-1T for the siding B is received at the left-hand end of the track section, Fig. 1D should be placed to the left of Fig. 1A. With the figures arranged in this manner, it will be noted that the reception of the 180 driven code causes the pulsing of contact 52 of relay 8TR (see Fig. 1D), and the pulsing of such contact causes the pulsing of relay 8TP. The pulsing of contact 53 of relay 8TP at a 180 rate causes the relays 8H and 8D to be normally energized in a manner corresponding to that described for the energization of the relays 2H and 2D, but the energization of such relays cannot be effective for causing the illumination of the green lamp of signal 8, because the circuit for such lamp is open at back contact 54 of relay 1HP.

Each time contact 55 of relay 8TR in its left-hand position is opened at the end of an impulse, the relay 8CP is picked up for the transmission of an inverse code impulse by the energization of a circuit extending from the left-hand terminal of the secondary winding of transformer 8FT including front contact 56 of relay 1H, back contact 57 of relay 1CS, front contact 58 of relay 8H, and winding relay 8CP, to (-). The reception of the 180 inverse code at the right-hand

end of track section 8-1T causes the pulsing of contact 46 of relay 1TR (see Fig. 1A), and the track repeater relay 1TP of course follows the pulsing of that contact. The pulsing of contact 59 of relay 1TP causes the picking up of relays 1H and 1D by the energization of circuits corresponding to those described for the energization of relays 2H and 2D except that the circuit for relay 1H includes normally closed contact 60 of the switch circuit controller for the track switch 1W. The energized condition of relays 1H and 1D does not cause the illumination of the green lamp of signal 1 under normal conditions as the circuit for such lamp is normally open at back contact 61 of relay 2HP.

A 180 driven code is normally transmitted from right to left through the track section 4-5T by the relay 5CP (see Fig. 1C) in accordance with the energization of such relay for each impulse of the oscillator C180. The circuit for relay 5CP under such conditions extends from (+), including contact 62 of relay 5TR in its left-hand position, contact 63 of oscillator C180, front contact 64 of relay 6H, and winding of relay 5CP, to (-). The pulsing of contact 65 of relay 5CP causes the transmission under normal conditions of a 180 driven code from right to left through the track section 4-5T by the energization of a track circuit corresponding to that which has been described for the track section 2-3T, such track circuit differing from the track circuit for track section 2-3T only in the inclusion of normally closed contact 66 of the track switch 2W which normally closes a circuit around the insulated joint 67.

The pulsing of contact 68 of relay 4TR (see Fig. 1B) upon the reception of the 180 driven code causes the relay 4TP to follow the code, and the pulsing of contact 69 of relay 4TP causes the relays 4H and 4D to be normally energized by the energization of circuits corresponding to those described for the energization of the relays 2H and 2D, respectively. The signal 4 is normally dark because of the open condition of back contact 70 of relay 3HP.

Each time the contact 71 of relay 4TR in its right-hand position is open, the relay 4CP is picked up for the transmission of an inverse code impulse from right to left through the track section 4-5T by the energization of a circuit extending from the left-hand terminal of the secondary winding of the transformer 4TF including front contact 72 of relay 3H, back contact 73 of relay 4CS, and winding of relay 4CP, to (-).

The reception at the right-hand end of the track section 4-5T of the inverse code causes the pulsing of contact 74 of relay 5TR (see Fig. 1C), and the pulsing of such contact causes the relay 5TP to follow the code. The pulsing of contact 74 of relay 5TP causes the relays 5H and 5D to be normally picked up by the energization of circuits corresponding to those which have been described for the relays 2H and 2D, respectively. The signal 5 is normally dark because of its circuit being open at back contact 75 of relay 6HP.

In accordance with the energized condition of the relay 5H, the code transmitter relay 6CP is normally active to transmit a 180 driven code from left to right through the track section 6-7T. The relay 6CP is energized for each impulse of the oscillator C180 by the energization of a circuit extending from (+), including contact 76 of relay 6TR in its right-hand position, contact 77 of oscillator C180, front contact 78 of re-

lay 5H, and winding of relay 6CP, to (-). The pulsing of contact 79 of relay 6CP at a 180 rate causes the transmission of a 180 driven code through track circuit of track section 6-7T by the energization of a track circuit corresponding to the track circuit described for the track section 2-3T.

At the right-hand end of the track section 6-7T (Fig. 1D placed to the right of Fig. 1C), the pulsing of contact 80 of relay 7TR (see Fig. 1D) causes the relay 7TP to follow the 180 code, and the pulsing of contact 81 of relay 7TP causes the picking up of the relays 7H and 1D by the energization of circuits corresponding to those which have been described for the relays 2H and 2D, respectively. The energized condition of the relays 7H and 1D causes the green lamp of signal 7 to be illuminated under normal conditions in accordance with the energization of a circuit extending from (+), including back contact 82 of relay 7CS, front contact 83 of relay 7H, front contact 84 of relay 1D, and the green lamp G of signal 7, to (-).

The conditions relative to the control of signal 8, and relative to code transmission and reception at the left-hand end of the track section 8-1T for the left-hand end of the siding C of course correspond to the conditions which have been described when Fig. 1D was considered to be placed at the left-hand end of Fig. 1A.

Passage of east-bound train

In order that the mode of operation of the system may be thoroughly described for a typical siding section and a typical stretch of single track between sidings, all of the conditions will be described which affect the siding section 8-1T for the siding B, and the sections of the stretch of single track between the sidings B and C. Therefore, to consider the conditions relative to the passage of an east-bound train through the siding section 8-1T, the Fig. 1D should be considered as being placed to the left of Fig. 1A so that the combination of the two figures discloses a complete siding section together with the signals and control apparatus for each end thereof. Upon considering the Figs. 1D and 1A in this relationship, the manner in which codes are transmitted through the track section 6-7T will not be considered, as it is believed that such conditions will be more readily understood as the description progresses when Fig. 1D will be assumed to be placed at the right of Fig. 1C in order that the Figs. 1A through 1D respectively may completely disclose the circuits associated with the stretch of single track between the sidings B and C.

It will be noted with reference to Fig. 3A that the presence of the train in the siding section 8-1T for the siding A does not affect the normal conditions for the siding section 8-1T for the siding B, but the entrance of the east-bound train into the stretch of single track between the sidings A and B as illustrated in Fig. 3B causes the removal of the inverse code transmitted through the track section 8-1T for the siding B. The manner in which the reversal in the direction of driven code transmission for the track section 6-7T becomes effective will be herein-after considered when considering in detail the mode of operation of the tumble-down for the opposing signals in the stretch of single track between the sidings B and C.

Although the inverse code transmitted from left to right through the track section 6-7T

maintains the relay 7H (see Fig. 1D) picked up, the signal 7 is put to stop because of the picking up of the relay 7CS which closes an obvious circuit for the red lamp of that signal at front contact 82, the opening of back contact 82 being effective to open the circuit which has been described for the green lamp of signal 7. The conditions under which the relay 7CS are picked up will be hereinafter considered when considering in detail the A. P. B. tumble-down.

The picking up of the relay 7CS is also effective to render the code transmitter 8CP inactive for the transmission of a code by the opening of back contact 51. The removal of the inverse code from the track section 8-1T for the siding B causes the dropping away of relays 1H and 1D (see Fig. 1A) but the dropping away of these relays has no apparent function if the trackway is unoccupied for some distance in advance of the east-bound train as is assumed under the conditions being described. The code transmitter 2CP for the left-hand end of track section 2-3T is unaffected by the dropping away of the relays H and D, as the circuit by which such relay is normally active for the transmission of a driven code does not include contacts of those relays.

As the east-bound train advances so as to occupy the track section 6-7T, the shunting of that track section causes the dropping away of the relays 1D and 7H (see Fig. 1D) at the right-hand end of the track section, but assuming there to be no trains in advance of the east-bound train, the dropping away of those relays does not affect the conditions of code transmission through the siding section 8-1T. The conditions under which the dropping away of the relays 7H and 1D due to the presence of an east-bound train in the track section 6-7T are dependent upon the presence of another train in advance, and they will be hereinafter considered.

The approach of the east-bound train to the signal 8, in causing the dropping away of the relay 7H, causes the dropping away of its repeater relay 7HP, and the dropping away of such relay renders the illumination of the green lamp effective for signal 8 by the energization of a circuit extending from (+), including back contact 54 of relay 7HP, front contact 85 of relay 8H, front contact 86 of relay 8D, and the green lamp of signal 8, to (-).

When the east-bound train enters the siding section 8-1T for the siding B as illustrated in Fig. 3E, the relays 8H and 8D are dropped away because of the shunting of the track section by the train. The shifting of contact 85 of relay 8H causes the extinguishing of the green lamp of signal 8, and causes the illumination of the red lamp of such signal by the energization of a circuit extending from (+), including back contact 54 of relay 7HP, back contact 85 of relay 8H, and the red lamp R of signal 8, to (-). It will be noted with reference to Fig. 3E that the normal conditions are restored for the track section 6-7T in the rear of the train, and the green lamp of signal 7 is illuminated. These conditions will be assumed to be effective for the present as a similar condition for the right-hand end section of the stretch of single track between the sidings B and C will be hereinafter described.

The presence of the east-bound train in the track section 8-1T of the siding B cannot of course affect the driven code transmitted toward the train, such code is still being transmitted, and in addition a 180 driven code is being transmitted from the left-hand end of the track section so as

to follow the train. The code transmitter for the left-hand end of the track section 8—1T is rendered active in accordance with the dropping away of the relay 8H for that end of the track section, and in accordance with the restoration to normal conditions for the track section 6—7T. The relay 8CP is therefore active for the transmission of a 180 driven code by the energization for each impulse of the oscillator C180 of a circuit closed from (+), including contact 52 of relay 8TR in its right-hand position, contact 87 of oscillator C180, back contact 88 of relay 7CS, front contact 89 of relay 7HP, back contact 58 of relay 8H, and winding of relay 8CP, to (—).

APB tumble-down

To consider further progress of the east-bound train along the trackway, it will be assumed that a train accepts the clear signal 2 and enters the track section 2—3T. Upon the shunting of such track section the relays 2H and 2D (see Fig. 1A) are dropped away, and the opening of front contact 36 of relay 2H causes the extinguishing of the green lamp of the signal 2. The red lamp of signal 2 is illuminated upon the energization of a circuit extending from (+), including back contact 35 of relay 2CS, back contact 36 of relay 2H, and the red lamp R of signal 2, to (—).

The dropping away of the relay 2H opens the circuit by which the relay 2CP has been active for the transmission of an inverse code at front contact 39, and the opening of front contact 34 of relay 2H causes the deenergization of the slow release repeater relay 2HP. Prior to the dropping away of the relay 2HP and subsequent to the dropping away of relay 2H, a circuit is closed by which the series relay 2SR is picked up due to the presence of the train in the track section 2—3T. The relay 2CP is momentarily energized under such conditions to close a circuit for the series relay 2SR by a circuit closed from (+), including back contact 34 of relay 2H, front contact 90 of relay 2HP, back contact 39 of relay 2H, back contact 40 of relay 2CS, and winding of relay 2CP, to (—). The relay 2SR is momentarily picked up by an impulse caused by the picking up of relay 2CP upon the energization of a circuit extending from the positive terminal of the track battery 41, including contact 25 of relay 2CP in its right-hand position, lower rail of track section 2—3T, the shunt provided by the presence of the train in the track section, upper rail of track section 2—3T, and winding of relay 2SR to the negative terminal of the track battery 41.

The picking up of the series relay 2SR prior to the dropping away of relay 2HP momentarily closes a pick-up circuit for the stick relay 2S extending from (+), including back contact 34 of relay 2H, front contacts 90 and 190 of relay 2HP, back contact 191 of relay 2CS, front contact 91 of relay 2SR, and winding of relay 2S, to (—). A stick circuit is closed for relay 2S when such relay is picked up, extending from (+), including back contact 34 of relay 2H, front contact 92 of relay 2S, and winding of relay 2S, to (—). The dropping away of the relay 2HP after the relay 2S has had time to pick up, causes the code transmitter relay 2CP to be dropped away by opening its circuit at front contact 90, and the opening of that front contact 90 and contact 190 of relay 2HP also opens the pick-up circuit which has been described for the stick relay 2S.

When the relay 2CP for the left-hand end of the track section 2—3T becomes inactive for the

transmission of an inverse code, the relays 3TR and 3TP (see Fig. 1B) for the right-hand end of that track section become inactive, and the relays 3H, 3HP and 3D are dropped away. The dropping away of such relays of course conditions the signal 3 for a stop indication, but such signal is maintained normally dark as it is not being approached by a train.

The dropping away of relay 3HP causes the energization of an obvious circuit for the green lamp G of signal 4, the relays 4H and 4D being picked up at that time.

Inasmuch as the code transmitter relay 4CP for the left-hand end of track section 4—5T is normally active for the transmission of an inverse code in accordance with the energized condition of the relay 3H, the opening of front contact 93 of relay 3H causes the relay 4CP to become inactive for the transmission of an inverse code from left to right through the track section.

In accordance with the removal of the inverse code from the track section 4—5T, the relays 5TR and 5TP (see Fig. 1C) at the right-hand end of the track section become inactive and the relays 5H, 5HP and 5D are dropped away.

The relay 6CP becomes inactive for the transmission of a driven code upon the opening of the circuit by which it has been normally active at front contact 18 of relay 5H. The relay 6CP by ceasing to be active removes the driven code formerly transmitted from left to right through the track section 6—7T (Fig. 1D placed at the right of Fig. 1C), and the removal of such code causes the relays 7TR and 7TP (see Fig. 1D) for the right-hand end of the track section to become inactive, and thus cause the dropping away of the relays 7H, 7HP and 7D.

The dropping away of relay 7H closes a circuit to cause the picking up of the code sending relay 7CS extending from (+), including contact 80 of relay 7TR in its left-hand position, back contact 94 of relay 7H, winding of relay 7CS, and back contact 95 of relay 7S, to (—). The picking up of the relay 7CS closes a stick circuit at front contact 96 for shunting back contact 94 of relay 7H out of the circuit just described. Such stick circuit provides the relay 7CS will be maintained picked up when the relay 7H is picked up upon the reception of an inverse code.

Upon the picking up of the code sending relay 7CS, a circuit is closed by which the code transmitter 7CP becomes active for the transmission of a driven code from right to left through the track section 6—7T extending from (+), including contact 89 of relay 7TR in its left-hand position, front contact 97 of relay 8H, front contact 98 of relay 8D, contact 99 of oscillator C180, front contact 100 of relay 7CS, and winding of relay 7CP, to (—).

The pulsing of contact 101 of relay 7CP for the transmission of a 180 driven code from right to left through the track section 6—7T under such conditions causes the relays 6TR (see Fig. 1C) and 6TP for the left-hand end of the track section to be active, and thus to cause the picking up of the relays 6H, 6HP and 6D. In accordance with the picking up of the relays 6H and 6D with the relay 5HP deenergized, a circuit is closed for the energization of the green lamp of signal 6, extending from (+), including back contact 102 of relay 5HP, front contact 103 of relay 6H, front contact 104 of relay 6D, and green lamp G of signal 6, to (—).

Conditions are established by the picking up

of the relay 6H whereby the code transmitter relay 6CP for the left-hand end of track section 6—7T becomes energized each time relay 7TR is deenergized. Relay 6CP is energized under such conditions by a circuit extending from the left-hand terminal of the secondary winding of transformer 6TF including back contact 105 of relay 5HP, front contact 106 of relay 6H, back contact 107 of relay 5S, back contact 78 of relay 5H, and winding of relay 6CP, to (—).

The reception of the inverse code thus transmitted through the track section 6—7T from left to right at the left-hand end of the track section causes the relays 7TR and 7TP (see Fig. 1D) to be active and thus to cause the picking up of the relays 7H, 7HP and 7D. The picking up of the relays 7H and 7D cannot be effective for causing the clearing of signal 7, as the circuits for the green and yellow lamps of such signal can be closed only upon the closure of back contact 82 of relay 7CS which is picked up at this time. The red lamp of signal 7 is illuminated when the code sending relay 7CS is picked up by the energization of an obvious circuit closed at front contact 82.

This operation of the track relay 7TR by inverse code pulses and the energization of the home relay 7H is used to detect the occupancy of the end track section 6—7T by an eastbound train for siding overlap control as discussed more fully later. Although the energization of this track relay 7TR intermittently opens its back contact 80 in the stick circuit for the code sending relay 7CS, this relay 7CS is provided with a supplemental stick circuit controlled by the operation of the coding contacts C180 or C75 at the proper times and in such a manner as to maintain this relay 7CS energized while the track relay 7TR is operated by inverse code pulses. For this purpose the coding contacts C180 and C75 governing the operation of the transmitter relay 7CP are provided with what may be termed back contacts which are closed when the ordinary contacts of the coding device are closed for the energization of transmitter relay 7CP to apply a driven code pulse. Assuming an eastbound train in the single track stretch and no other trains ahead, as indicated in Fig. 3C, the supplemental stick circuit for the code sending relay 7CS (Fig. 1D) controlled by the coding contact C180 may be traced from (+), through back contact of the coding contacts C180 closed as shown, front contacts 98 and 97 of relays 8D and 8H, front contact 96 of relay 7CS, winding of this relay, and back contact 95 of relay 7S to (—).

Considering the operation of this organization for the control of the code sending relay 7CS, the driven code pulses are applied when the transmitter relay 7CP is energized by movement of the contact finger of the coding contacts C180 to the left in engagement with contact 99; and since the inverse code pulses operate the track relay 7TR during the "off" intervals between the successive driven code pulses, said contact finger will be in the right-hand position supplying energy in multiple with the back contact 80 of the track relay 7TR to hold up the relay 7CS by the supplemental stick circuit during the time interval this back contact 80 is opened by an inverse code pulse. In other words, there are in effect two stick circuits for the code sending relay 7CS, one including a back contact 80 of the track relay 7TR, and the other including the back contact of the coding contact C180 or C75 then in effect;

and since the energization of the track relay 7TR by inverse code pulses occurs alternately and in synchronism with the operation of the coding contacts, these two stick circuits are closed alternately and in overlapping relation to maintain the code sending relay 7CS energized.

Although the conditions under which the code sending relay 7CS is released are considered later, it may be pointed out here that any energization of the track relay 7TR at a time other than during the regular "off" period for the driven code in effect, such as would be caused by an opposing and overlapping driven code pulse, will automatically release the relay 7CS by holding open the back contact 80 of the track relay 7TR at the time when the coding contacts C180 or C75 operate for the next driven code pulse. In this connection, it should be noted that operation of the coding contacts C180 or C75 for the next driven code pulse is not effective to energize the transmitter relay 7CP under these conditions, since the back contact 80 of track relay 7TR is open, and the energizing circuit for the transmitter relay 7SP previously described includes this contact 80. Consequently, any energization of the track relay 7TR prolonged beyond the "off" interval of the driven code, as by an opposing driven code pulse, is effective for its full duration independently of the operation of the coding contacts C180 or C75.

The same circuit organization and mode of operation just described for the code sending relay 7CS also applies to the code sending relay 2CS for the other end of the single track stretch.

35 The circuit by which the code transmitter relay 8CP is normally active for the transmission of an inverse code from left to right through the track section 8—1T is opened at back contact 57 of relay 7CS upon the picking up of that relay, and therefore the inverse code normally transmitted from left to right through the track section 8—1T is removed. The removal of the inverse code causes the H and D relays for the right-hand end of the track section to be dropped away in a manner and for purposes corresponding to those which have been described under corresponding traffic conditions where it was assumed that an eastbound train had entered the stretch of single track between sidings A and 50 B as illustrated in Fig. 3B.

Passage of east-bound train through stretch between sidings

When the progress of the east-bound train is such as to cause the track section 8—1T (Fig. 1D placed at the right of Fig. 1A) to become unoccupied in the rear of the train, there is a "code fight" between the driven code transmitters for the opposite ends of such track section, and the arrangement of the circuits is such that the transmitter for the right-hand end of the track section over-rules the transmitter for the left-hand end thereof. At the right-hand end of the track section the energized condition of the stick relay 2S (see Fig. 1A) with the relay 2HP dropped away is effective to cause the code transmitter relay 1CP for the right-hand end of track section 8—1T to be picked up for each impulse of the oscillator C120 by the energization of a circuit extending from (+), including contact 46 of relay 1TR in its left-hand position, contact 108 of oscillator C120, front contact 109 of relay 2S, back contact 49 of relay 2HP, normally closed contact 50 of the switch circuit controller for the track switch 1W, and winding of relay

ICP, to (-). It will be noted that the energization of either of the relays 1H or 1D cannot affect the circuit just described for the relay ICP. However, at the left-hand end of the track section 8-1T, the energization of the relay 8H (see Fig. 1D) upon reception of an impulse of the driven code transmitted from the right-hand end of the track section, is effective upon the opening of back contact 58 to render the code transmitter relay 8CP for the left-hand end of the track section inactive for the transmission of the driven code. In this manner the "code fight" is solved in favor of the code transmitter for the right-hand end of the track section. The energization of the relay 8H, with the relay 1CS dropped away and the relay 1H picked up, establishes a circuit which has been described when considering the normal conditions of the system by which the relay 8CP becomes active for the transmission of an inverse code.

The reception of the inverse code at the right-hand end of track section 8-1T is effective to cause the picking up of the relay 1H, but the relay 1D is not picked up because of the 120 code selected for the driven code by the energized condition of the stick relay 2S. The picking up of relay 1H under such conditions opens the circuit for the red lamp R of signal 1 at back contact 110, and closes a circuit by which the yellow lamp of such signal is energized extending from (+), including back contact 61 of relay 2HP, front contact 110 of relay 1H, back contact 111 of relay 1D, and the yellow lamp Y of signal 1, to (-). By the display of a caution indication in this manner, means is provided whereby the east-bound train occupying the track section 2-3T can reverse its direction if desired.

To consider further progress of the east-bound train, it will be assumed that the train accepts the clear signal 4 and enters the track section 4-5T. The signal 4 has been cleared with the train in approach thereto because of the closure of back contact 70 of relay 3HP with the relays 4H and 4D picked up. The shunting of track section 4-5T causes the dropping away of the relays 4H and 4D, and therefore the green lamp of signal 4 is extinguished upon the opening of front contact 112 of relay 4H. The closure of back contact 112 of relay 4H closes an obvious circuit for the red lamp R of that signal.

By a mode of operation similar to that which has been described for the passage of the east-bound trains past signal 2, the stick relay 4S is picked up when the train enters the track section 4-5T. The series relay 4SR is momentarily energized for the picking up of the stick relay 4S by the momentary energization of the code transmitter relay 4CP for an impulse of sufficient length to allow for the picking up of the series relay 4SR and the stick relay 4S. The impulse of the relay 4CP is dependent upon the momentary picking up of the code sending relay 4CS, and the momentary energization of such code sending relay is dependent upon the dropping away of the slow acting repeater relay 4HP subsequent to the dropping away of the relay 4H. Thus, the relay 4CS is momentarily picked up upon the dropping away of the relay 4H by the energization of a circuit extending from (+), including back contact 113 of relay 4H, front contact 114 of relay 4HP, winding of relay 4CS, and back contact 115 of relay 4S,

to (-). Upon the picking up of relay 4CS under such conditions, the relay 4CP is picked up by the energization of a circuit extending from (+), including back contact 116 of relay 4H, front contact 117 of relay 4HP, back contact 118 of relay 3HP, back contact 119 of relay 3S, back contact 93 of relay 3H, front contact 73 of relay 4CS, and winding of relay 4CP, to (-). The closure of contact 121 of relay 4CP in its right-hand position with the track section 4-5T shunted by the train causes the picking up of the series relay 4SR by the energization of an obvious circuit.

Upon the picking up of the series relay 4SR, a circuit is closed to cause the picking up of the stick relay 4S extending from (+), including back contact 116 of relay 4H, front contact 117 of relay 4HP, back contact 118 of relay 3HP, front contact 122 of relay 4SR, and winding of relay 4S, to (-). A stick circuit is closed for such relay after it has been picked up extending from (+), including back contact 116 of relay 4H, front contact 123 of relay 4S, and winding of relay 4S, to (-). The picking up of relay 4S opens the circuit which has been described by which the relay 4CS has been picked up at back contact 115, and the dropping away of the relay 4CS opens the circuit by which the relay 4CP has been energized at front contact 123. The opening of contact 121 of relay 4CP in its right-hand position causes the dropping away of the series relay 4SR, and the dropping away of such relay opens the pick-up circuit which has been described for the stick relay 4S at front contact 122. The pick-up circuit for relay 4S is also opened at front contact 117 of relay 4HP when such relay is dropped away.

When the track section 2-3T becomes unoccupied in the rear of the train, a 75 driven code transmitted through the track section from right to left is effective to cause the energization of the H relay at the left-hand end of the track section, and the transmission of an inverse code from right to left is effective to cause the picking up of the relay 3H at the right-hand end of the track section. The code transmitter relay 3CP (see Fig. 1B) is active for the transmission of a 75 driven code under such conditions in accordance with the picked up condition of the stick relay 4S by the energization of a circuit for each impulse of the oscillator C75 closed from (+), including contact 20 of relay 3TR in its left-hand position, contact 124 of oscillator C75, front contact 125 of relay 4S, back contact 22 of relay 4H, and winding of relay 3CP, to (-).

The reception of the 75 driven code at the left-hand end of track section 2-3T causes the picking up of relay 2H (see Fig. 1A), but the relay 2D remains dropped away because of the 75 code received. The picking up of the relay 2H at the left-hand end of the track section 2-3T is effective to cause the stick relay 2S to be dropped away by opening the stick circuit for such relay at back contact 34, and the energized condition of the relay 2H is also effective to cause the code transmitter relay 2CP to be effective for the transmission of an inverse code from right to left through the track section 2-3T by the energization of a circuit which has been described when considering the normal conditions of the system.

When the relay 2H is picked up, the circuit for the red lamp R of signal 2 is opened at back contact 36, and a circuit is closed for the energization of the yellow lamp of such signal ex-

tending from (+), including back contact 35 of relay 2CS, front contact 36 of relay 2H, back contact 37 of relay 2D, and the yellow lamp Y of signal 2, to (-).

The energization of the relay 2H for the left-hand end of the track section 2-3T is effective to change the driven code transmitted from right to left through the track section 8-1T and from a 120 code to a 180 code. The energization of the relay 1CP for each impulse of the oscillator C180 is effective by the closure of a circuit which has been described when considering the normal conditions of the system. The change of the inverse code transmitted from left to right through such track section causes the picking up of the relay 1D, but the signal 1 is maintained dark because of the energized condition of the relay 2HP. At the left-hand end of the track section, the shifting of the code from a 120 code to a 180 code causes the dropping away of the relay 8DX (Fig. 1D placed to the left of Fig. 1A) and the energization of the relay 8D because of the manner in which the circuits for such relays are respectively tuned. The effect of the change in the conditions of these relays will be more readily apparent as progress of the east-bound train is considered after the train has been assumed to leave the stretch of single track between the sidings B and C.

At the right-hand end of the track section 2-3T, the reception of the inverse code at a 75 rate causes the picking up of the relay 3H (see Fig. 1B), but the relay 3D remains dropped away. The energization of the relay 3H causes the opening of the circuit for the red lamp R of signal 3 at back contact 126, and the closure of front contact 126 causes the yellow lamp of such signal to be energized by an obvious circuit selected by the deenergized condition of the relay 3D.

When the east-bound train accepts the signal 6 and enters the track section 6-7T, the dropping away of relay 6H (see Fig. 1C) is effective to open the circuit for the green lamp of signal 6 at front contact 103, and close an obvious circuit for the red lamp of that signal at back contact 103. The relay 6CP has been active for the transmission of an inverse code from left to right through the track section 6-7T prior to the entrance of the train into the track section, but the dropping away of the relay 6H is effective to open the circuit by which the relay 6CP has been active at front contact 106. A circuit is closed for the momentary energization of the relay 6CP in order to provide a means for picking up the stick relay 6S extending from (+), including back contact 127 of relay 6H, front contact 128 of relay 6HP, back contact 129 of relay 5HP, back contact 106 of relay 6H, back contact 107 of relay 5S, back contact 18 of relay 5H, and winding of relay 6CP, to (-). The actuation of the contact 18 of relay 6CP to its right-hand position causes the energization of the series relay 6SR, because of the presence of the train in the track section 6-7T, by the energization of an obvious circuit. When the series relay 6SR is picked up, the stick relay 6S is picked up by the energization of a circuit corresponding to that which has been described for the picking up of the stick relay 4S, and the picking up of such stick relay closes a stick circuit at back contact 128 of relay 6HP to maintain the relay picked up until the energization of the relay 6HP has become effec-

tive. The dropping away of the slow acting relay 6HP terminates the period by which the relay 6CP has been energized upon the opening of front contact 128, and the dropping away of the series relay 6SR opens the pick-up circuit for the stick relay 6S at front contact 130. The pick-up circuit for relay 6S is also opened at front contact 128 of relay 6HP when such relay is dropped away.

10 The relay 5CP becomes active for the transmission of a 75 driven code from right to left through the track section 4-5T in accordance with the picking up of the stick relay 6S by the energization of a circuit for each impulse of the oscillator C15 extending from (+), including contact 62 of relay 5TR in its left-hand position, contact 131 of oscillator C15, front contact 132 of relay 6S, back contact 64 of relay 6H, and winding of relay 5CP, to (-). The reception at 15 the left-hand end of track section 4-5T of the 75 code after the track section has become occupied in the rear of the east-bound train causes the picking up of the relay 4H (see Fig. 1B), but the relay 4D remains dropped away. The picking up of relays 4H and 4HP is effective to complete restoration to the normal conditions for the track section 2-3T, the picking up of relay 4H being effective to restore the 180 driven code normally transmitted through the track section, 20 and the picking up of relay 4HP being effective to open the circuits for the indicator lamps of signal 3 to cause that signal to be restored to its normally dark condition. The relay 4S is dropped away upon the picking up of relays 4H and 4HP by the opening of back contacts 116 and 117, respectively, and the dropping away of relay 4S opens the circuit by which the relay 3CP has been active for the transmission of a 75 code at front contact 125. The relay 3CP is 25 active for the transmission of a 180 driven code upon the closure of front contact 22 of relay 4H by the energization of a circuit which has been described when considering the normal conditions of the system.

30 Upon the reception of the 75 driven code at the left-hand end of the track section 4-5T, the code transmitter relay 4CP becomes active for the transmission of an inverse code from left to right through that track section by the energization of a circuit which has been described when considering the normal conditions of the system.

35 At the right-hand end of the track section, the relays 5H and 5HP are picked up, but the relay 5D remains dropped away because of the 75 code being transmitted. The red lamp of signal 5 is therefore extinguished by the opening of back contact 133 of relay 5H, and the yellow lamp of such signal is illuminated by the energization of a circuit extending from (+), including back contact 75 of relay 6HP, front contact 133 of relay 5H, back contact 134 of relay 5D, and yellow lamp Y of signal 5, to (-).

40 When the east-bound train enters the track section 6-7T (Fig. 1D placed to the right of Fig. 1C), the shunting of the track section causes the dropping away of the relays 7H and 7HP (see Fig. 1D) when the pulsing of contact 81 of relay 7TP ceases, but this will not affect the opposing signal 7, as such signal has been 45 at stop because of the closure of front contact 82 of the code sending relay 7CS. Although the dropping away of the relays 7H and 7HP under the traffic conditions considered at present does not affect the codes transmitted through the 50 siding section, it will be hereinafter described.

how the dropping away of such relays can affect the code transmitted through the siding track section 8-1T for the control of the entering signal at the opposite end of the siding when such entering signal is being approached by a west-bound train. Such conditions are dependent upon the reversal in the direction of code transmission through the siding section as would be rendered effective by the presence of the west-bound train in approach of the west-bound entering signal for the siding.

The presence of the east-bound train in the track section 6-7T in causing the dropping away of the relays 7H and 7HP provides for the illumination of the green lamp of signal 8 by the energization of an obvious circuit closed at back contact 54 of relay 7HP. The code transmitter for the right-hand end of the track section 6-7T continues to be active for the transmission of a driven code in a manner which has been described, and also the transmitter for the left-hand end of the track section is rendered active upon the picking up of the relay 5H for the right-hand end of track section 4-5T so as to transmit a driven code from left to right in the track section 6-7T. This condition is illustrated by the direction arrows indicative of the direction of driven code transmission for the track section 6-7T as illustrated in Fig. 3D for the east-bound train approaching the siding B. Inasmuch as the presence of the train in the track section causes the relay 7TR to be inactive, the relay 7CS for the right-hand end of the track section is maintained steadily energized by a circuit closed at contact 80 of relay 7TR in its left-hand position.

When the east-bound train accepts the signal 8 and enters the track section 8-1T associated with the siding C, the signal 8 is put to stop in accordance with the dropping away of the relays 8H and 8D in a manner corresponding to that which has been described upon the acceptance of an east-bound train of the entering signal 8 for the siding B.

When the train under consideration passes the signal 8 and out of the single track stretch, as indicated in Fig. 3E, the home relay 8H is de-energized and its back contact 97 is closed to render the coding contact C75 effective to govern the energization of the transmitter relay 7CP to provide a caution or 75 code for the control of the intermediate signal 6 next in the rear. Assuming no following train, the transmitter relay 6CP at the other or left-hand end of the track section 6-7T is being operated to provide code pulses at the 180 code rate behind the train, as indicated in Fig. 3D. Consequently, when the eastbound train in question leaves the track section 6-7T, there is a temporary conflict between two driven codes created by the transmitter relays 6CP and 7CP at the opposite ends of this track section which are being operated at different code rates and by independently operating coding contacts. Under these conditions, the impulses supplied by transmitter relay 6CP and energizing the track relay 7TR are not timed like inverse code pulses to fit in the "off" intervals between the operations of the coding contacts controlling the transmitter relay 7CP, but may occur at any time and will be prolonged beyond such "off" intervals, within a short time dependent upon the time relationship of the operation of the coding contacts governing the transmitter relays 6CP and 7CP. Consequently, an energization of the track relay 7TR will

quickly occur under the conditions in question, and release the code sending relay 7CS in a manner previously explained.

Upon the dropping away of the relay 7CS, the circuit by which the code transmitter 7CP has been active is open at front contact 100, thus terminating the transmission of a driven code from the right-hand end of the track section. The reception of the 180 driven code transmitted from left to right through the track section causes the relays 7TR and 7TP to be active so as to cause the picking up of the relays 7H, 7HP and 7D, and the picking up of such relays causes the clearing of signal 7 by the energization of a circuit which has been described when considering the normal conditions of the system, the red lamp for the signal 7 being extinguished upon the opening of front contact 82 of the code sending relay 7CS. In accordance with the picking up of the relay 7H, with the code sending relay 7CS dropped away, the relay 7CP becomes active for the transmission of an inverse code from right to left through the track section 6-7T by the energization of a circuit which has been described when considering the normal conditions of the system.

The reception of the inverse code at the left-hand end of the track section 6-7T causes the picking up of the relays 6H, 6HP and 6D (see Fig. 1C), and the picking up of those relays completes the restoration to the normal conditions for the control apparatus associated with the track section 6-7T. The picking up of relay 6HP causes the signal 5 to be dark because of the opening of back contact 75, and the signal 6 is dark because back contact 102 of relay 5HP is open under the assumed conditions. Upon the picking up of relays 6H and 6HP, the opening of back contacts 127 and 128, respectively, cause the dropping away of the stick relay 6S. The shifting of contact 64 of relay 6H opens the circuit by which the relay 5CP has been active for the transmission of a 75 driven code from right to left through the track section 4-5T and closes a circuit which has been described when considering the normal conditions of the system whereby the relay 5CP becomes active for the transmission of a 180 driven code. The shifting of the code rate in the track section 4-5T causes the picking up of the relay 4D for the left-hand end of the track section, and causes the picking up of the relay 5D for the right-hand end of the track section.

As the east-bound train proceeds further along the trackway so as to leave the track section 8-1T unoccupied in the rear of the train, a 120 driven code is transmitted from right to left through the track section so as to cause the picking up of the relays 8H and 8DX at the left-hand end of the siding C. The energization of the relay 8DX is effective to select a 180 driven code for transmission from right to left through the track section 6-7T for the clearing of the intermediate signal 6 in case a following east-bound train enters the stretch of single track between the sidings B and C. This condition will be hereinafter considered more in detail.

Passage of west-bound trains

After having considered in detail the mode of operation upon passage of an east-bound train, it is believed to be readily apparent from the diagrams of Figs. 4A through 4F that the mode of operation for the passage of a west-bound train is somewhat similar. It is therefore be-

lieved unnecessary to describe those similar conditions, but the passage of a west-bound train will hereinafter be considered sufficiently in detail to point out the mode of operation which is not comparable to similar traffic conditions which have been considered for the passage of an east-bound train. Upon considering the passage of a west-bound train, the conditions affecting the signals associated with the siding B will be considered together with the conditions associated with the passage of the train through the stretch of single track between sidings A and B. To consider the circuits associated with the siding section for the siding B, Fig. 1A is to be placed at the right of Fig. 1D.

The entrance of a west-bound train into the stretch of single track between the sidings B and C changes the driven code transmitted through the siding section 8-1T for the siding B from a 180 code to a 75 code in order to provide the usual double caution opposing signal protection characteristic of most absolute-permissive-block signaling systems. The picking up of the relay 2CS for the left-hand end of the end track section adjacent the siding B in the stretch of single track between the sidings B and C is effective to open the circuit by which the code transmitter relay 1CP (see Fig. 1A) has been normally active for the transmission of a 180 driven code at back contact 48, and to close a circuit at front contact 48 by which the relay is active for the transmission of a 75 driven code. Such circuit is closed from (+); including contact 46 of relay 1TR in its left-hand position, contact 135 of oscillator C75, front contact 48 of relay 2CS, front contact 49 of relay 2HP, normally closed contact 50 of the switch circuit controller for the track switch 1W, and winding of relay 1CP, to (-).

At the left-hand end of the track section 8-1T for the siding B, the change in the code transmitted causes the dropping away of the relay 8D, and the deenergized condition of that relay, with the relay 8DX dropped away, conditions a circuit by which a 75 driven code would be transmitted from right to left through the track section 6-7T if an opposing east-bound train were to enter the stretch of single track between the sidings A and B so as to cause a reversal in the direction of driven code transmission through the track section 6-7T. The transmission of a 75 driven code through that track section under such conditions would cause the signal 6 to be put to caution.

It will be noted with reference to Fig. 4B that the passage of the west-bound train into the intermediate track section in the stretch of single track between the sidings B and C does not affect the codes transmitted through the siding track section associated with the siding B, but the entrance of the train into the end track section adjacent the siding as illustrated in Fig. 4C causes a reversal in the direction of driven code transmission in the siding section.

Upon the entrance of the west-bound train into the end section adjacent the right-hand end of the siding B, the dropping away of the relay 2HP is effective to open the circuit by which the relay 1CP has been active for the transmission of a driven code at front contact 49. The removal of the driven code from the track section 8-1T causes the dropping away of the relay 8H at the left-hand end of the track section, and the dropping away of such relay closes a circuit by which the relay 8CP becomes active for the transmission of a 180 driven code, it being assumed that the trackway is unoccupied for some

distance in advance of the west-bound train. The relay 8CP is energized for each impulse of the oscillator C180 for the transmission of a 180 driven code by the closure of a circuit extending from (+), including contact 52 of relay 8TR in its right-hand position, contact 87 of oscillator C180, back contact 88 of relay 7CS, front contact 89 of relay 7HP, back contact 58 of relay 8H, and winding of relay 8CP, to (-). The reception of the 180 driven code at the right-hand end of track section 8-1T is effective to cause the picking up of relays 1H and 1D, and the picking up of those relays, with the relay 2HP dropped away, closes an obvious circuit for the energization of the green lamp of signal 1.

When the west-bound train accepts the signal 1 and enters the siding section 8-1T, the dropping away of the relays 1H and 1D due to the shunting of the track section causes the extinguishing of the green lamp of signal 1 and the illumination of the red lamp of such signal in a manner similar to that which has been described when considering the passage of an east-bound train past an entering signal. It will be noted according to Fig. 4E that the entrance of a west-bound train into a siding section renders the code transmitter relay active for the transmission of a driven code for the right-hand end of that section. The transmission of the driven code from right to left in the track section 8-1T is rendered effective when the end track section in the rear of the train becomes unoccupied, and the normal conditions for such end section are restored. In accordance with the restoration of such conditions, the relay 1CP becomes active for the transmission of a driven code by the energization of a circuit which has been described when considering the normal conditions of the system.

To consider further progress of the west-bound train, it will be assumed that such train accepts the signal 7 (see Fig. 1D) which is normally clear and enters the stretch of single track between the sidings B and C. Upon the entrance of the train into the track section 6-7T the signal 7 is put to stop upon the dropping away of the relays 7H and 7D, and the dropping away of those relays also renders the code transmitter relay 7CP inactive for the transmission of an inverse code by opening its circuit at front contact 136 of relay 7H. The relay 7CP is picked up, however, for a single pulse upon the dropping away of the relay 7H in order to provide for the momentary energization of the series relay 7SR. Under such conditions the relay 7CP is picked up by the energization of a circuit extending from (+), including back contact 137 of relay 7H, front contact 138 of relay 7HP, back contact 136 of relay 7H, back contact 100 of relay 7CS, and winding of relay 7CP, to (-). Upon the picking up of the series relay 7SR because of the presence of the train in the right-hand end of the track section 6-7T, the directional stick relay 7S is energized by a circuit similar to those previously described for the directional stick relay 2S. The picking up of the stick relay 7S prevents the energization of the code sending relay 7CS by opening the circuit for such relay at back contact 95.

The shunting of the track section 6-7T causes the dropping away of the relays 6H, 6HP and 6D (see Fig. 1C) at the left-hand end of the track section. The dropping away of the relay 6H opens the circuit by which the relay 5CP has been active for the transmission of a 180 driven

code at front contact 64, and therefore the driven code is removed from the track section 4-5T. It will be noted in the circuit for the relay 5CP that the circuit including back contact 64 of relay 6H cannot be closed when the relay 6H is first dropped away because of the inclusion of back contact 141 of the slow acting repeater relay 6HP in the circuit which is provided for the momentary energization for a single impulse of the relay 5CP in connection with the control of the stick relay 5S. Thus in changing the direction of driven code transmission in the track section 4-5T it is provided that the code transmitter relay 5CP could not be picked up even if the momentary interruption in the energy for the relay 5H were effective to cause that relay to be momentarily dropped away.

The removal of the driven code from the track section 4-5T causes the dropping away of the relays 4H, 4HP and 4D (see Fig. 1B) at the left-hand end of the track section, and the dropping away of the relay 4H prior to the dropping away of the relay 4HP closes a circuit by which the code sending relay 4CS is picked up. Such circuit extends from (+), including back contact 113 of relay 4H, front contact 114 of relay 4HP, winding of relay 4CS, and back contact 115 of relay 4S, to (-). A stick circuit for maintaining the code sending relay 4CS energized until a driven code is received at that end of the track section is closed from (+), including contact 71 of relay 4TR in its right-hand position, front contact 142 of relay 4CS, winding of relay 4CS, and back contact 115 of relay 4S, to (-).

Upon the picking up of the relay 4CS, with the trackway unoccupied in advance of the west-bound train, the relay 4CP is rendered active to transmit a 180 driven code from left to right through the track section 4-5T in accordance with the energization of its circuit for each impulse of the oscillator C180. Such circuit is closed from (+), including contact 71 of relay 4TR in its right-hand position, contact 143 of oscillator C180, front contact 93 of relay 3H, front contact 73 of relay 4CS, and winding of relay 4CP, to (-). The circuit by which the relay 4CP has been active for the transmission of an inverse code is opened upon the picking up of the relay 4CS at back contact 73. At the right-hand end of the track section 4-5T, the reception of the 180 driven code is effective to cause the relays 5H, 5HP and 5D (see Fig. 1C) to be energized, and with the relay 6HP dropped away, an obvious circuit is closed at back contact 75 for the energization of the green lamp of signal 5.

The code transmitter relay 3CP is rendered inactive for the transmission of a driven code upon the opening of its circuit at front contact 22 of relay 4H when such relay is dropped away. The driven code is thus removed from the track section 2-3T. The removal of such driven code causes the relays 2H, 2HP and 2D (see Fig. 1A) at the left-hand end of the track section 2-3T to be dropped away, and the dropping away of the relay 2H is effective to cause the picking up of the code sending relay 2CS for reversing the direction of code transmission in the track section 2-3T in a manner which can be readily identified as corresponding to that which has been described for the reversal in the direction of driven code transmission in the end section 6-7T when considering the passage of an east-bound train. When the code transmitter relay 2CP becomes active to transmit a driven code from left to right through the track section 2-3T, the

relay 3CP at the right-hand end of the track section becomes active for the transmission of an inverse code because of its energization each time the relay 3TR is deenergized by a circuit extending from the right-hand terminal of the secondary winding of transformer 3TF (see Fig. 1B) including back contact 144 of relay 4HP, front contact 145 of relay 3H, back contact 125 of relay 4S, back contact 22 of relay 4H, and winding of relay 3CP, to (-). It will be noted that the inclusion of back contact 144 of relay 4HP in the circuit just described allows time for the reversal in the direction of driven code transmission to become effective to prevent any possibility of regeneration due to the inverse code formerly transmitted from left to right through the track section. The reception of the inverse code thus established for transmission from right to left through the track section 2-3T at the left-hand end of the track section causes the relays 2H and 2D (see Fig. 1A) to be again picked up, but the signal 2 displays a stop indication because of the closure of front contact 35 of the code sending relay 2CS to provide for the energization of the red lamp of such signal. The transmission of the inverse code from right to left through the track section 2-3T under such conditions is effective to detect track occupancy at the left-hand end of the track section 2-3T, with the signal 2 at stop, in order to provide single block siding overlap control for the entering signal at the left-hand end of the siding A in a manner and for purposes heretofore more specifically pointed out with reference to the conditions involving the passage of an east-bound train.

In accordance with the entrance of a west-bound train into the stretch of single track between the sidings B and A, the driven code normally transmitted from right to left through the siding section 8-1T (Fig. 1D placed to the left of Fig. 1A) for the siding A is changed from a 180 code to a 75 code to provide for the double caution opposing signal protection at the left-hand end of the siding. The code transmitted in the track section is changed from a 180 driven code to a 75 driven code in accordance with the shifting of contact 48 of the code sending relay 2CS when the tumble-down through the stretch of single track has been completed. The relay 1CP becomes active for the transmission of a 75 driven code because of the energization for each impulse of the oscillator C75 of a circuit closed from (+), including contact 46 of relay 1TR in its left-hand position, contact 135 of oscillator C75, front contact 48 of relay 2CS, front contact 49 of relay 2HP, normally closed contact 50 of the switch circuit controller for the track switch 1W, and winding of relay 1CP, to (-). The changing of the code in the track section 8-1T for the siding A to a 75 code causes the dropping away of the relay 8D at the left-hand end of the track section, and the dropping away of such relay would be effective to cause the transmission of a 75 driven code in the track section 6-7T for the caution indication of signal 6 if an opposing east-bound train were approaching such signal in a manner illustrated, for example, in Fig. 7A. The presence of such opposing train will not be considered at this time, however, and it will be assumed that the trackway in advance of the west-bound train is unoccupied.

The stick relay 1S (see Fig. 1D) for the leaving signal 7 associated with siding B is picked up upon passage of the west-bound train past

that signal, and the mode of operation for the energization of that relay corresponds to that which has been described in detail for the energization of the stick relay 2S (see Fig. 1A) when an east-bound train has been assumed to accept the entering signal 2.

When the siding section 8-1T for the siding B becomes unoccupied in the rear of the west-bound train, there is a code fight between the transmitters for the opposite ends of the siding section, and the code transmitter for the right-hand end thereof is effective to over-rule the code transmitter for the left-hand end to restore the normal conditions of code transmission for the siding section. Such restoration to normal is effective only if the trackway is unoccupied for a considerable distance in the rear of the train, as the approach to signal 1 of a following west-bound train would cause the direction of driven code transmission to be established from left to right in the siding section in a manner which will be hereinafter considered. Under such traffic conditions, the code transmitted for the control of signal 1 would be a 75 code as illustrated in Fig. 6C.

Upon considering further progress of the west-bound train, it will be assumed that the train accepts the clear signal 5 and enters the track section 4-5T. The shunting of such track section causes the dropping away of the relays 5H, 5HP and 5D (see Fig. 1C), and the dropping away of relay 5H prior to the dropping away of relay 5HP, closes a circuit by which the code transmitter relay 5CP is picked up for a single impulse in order to effect the picking up of the stick relay 5S. The circuit for relay 5CP under such conditions extends from (+), including back contact 146 of relay 5H, front contact 147 of relay 5HP, back contact 141 of relay 6HP, back contact 132 of relay 6S, back contact 64 of relay 6H, and winding of relay 5CP, to (-). The actuation of the contact 65 of relay 5CP to its left-hand position causes the picking up of the series relay 5SR, and the picking up of such relay closes a circuit by which the relay 5S is picked up extending from (+), including back contact 146 of relay 5H, front contact 147 of relay 5HP, back contact 141 of relay 6HP, front contact 148 of relay 5SR, and winding of relay 5S, to (-). An obvious stick circuit is closed for the relay at front contact 149 to shunt contacts 148, 141 and 147 out of the circuit which has just been described.

When the track section 6-7T becomes unoccupied in the rear of the train, the normal direction of code transmission in the track section is established in a manner corresponding to the restoration in track section 2-3T for a similar traffic condition associated with the passage of an east-bound train. The driven code transmitted from left to right through the track section is a 75 code selected by the stick relay 5S. The relay 6CP is active for the transmission of such code by the energization of a circuit for each impulse of the oscillator C15 extending from (+), including contact 76 of relay 6TR in its right-hand position, contact 150 of oscillator C15, front contact 107 of the stick relay 5S, back contact 78 of relay 5H, and winding of relay 6CP, to (-).

The code transmitter relay 5CP for the right-hand end of the track section 4-5T is rendered active for the transmission of a 180 driven code when the track section 6-7T becomes unoccupied in the rear of the train. The relay 5CP is energized under such conditions for each impulse of

the oscillator C180 in an obvious manner in accordance with the closure of front contact 64 of relay 6H.

When the west-bound train enters the track section 2-3T (Fig. 1A placed to the left of Fig. 1B), the relays 3H and 3D (see Fig. 1B) are dropped away and the dropping away of relay 3H initiates the conditions required for the picking up of the stick relay 3S. The manner in which the stick relay 3S is picked up corresponds to that which has been described for the picking up of the relay 5S upon the entrance of the west-bound train into the track section 4-5T.

The relay 4CP is rendered active for the transmission of a 75 driven code in the track section 4-5T upon the picking up of the relay 3S by the energization of a circuit for each impulse of the oscillator C15 extending from (+), including contact 71 of relay 4TR in its right-hand position, contact 151 of oscillator C15, front contact 119 of relay 3S, back contact 93 of relay 3H, front contact 73 of relay 4CS, and winding of relay 4CP, to (-). Thus, there is a code fight between the transmitters for the opposite ends of the track section 4-5T when such track section becomes unoccupied by the train, and the code transmitter for the right-hand end of the track section is effective to over-rule the code transmitter for the left-hand end thereof upon the opening of the stick circuit for the code sending relay 4CS at contact 71 of relay 4TR in its right-hand position when an impulse is received at the left-hand end of the track section 4-5T. A momentary energization of the track relay 4TR is sufficient to release the code sending relay 4CS, and such energization will occur quickly as soon as the train clears the track section 4-5T, because the code following up this train is at the 180 rate, while the transmitter relay 4CP intermittently connecting the track relay 4TR to the track rails is being operated at the 75 code rate with the directional stick relay 3S energized, and a pulse of the 180 code is bound to occur and pick up track relay 4TR during an "off" period of the 75 code. In this connection, it should be noted that the energizing circuit for the transmitter relay 4CP includes a back contact 71 of the track relay 4TR; and once this track relay is energized by a code pulse at the 180 rate during an "off" interval of the 75 code, this track relay is maintained energized for the full duration of such 180 code pulse, regardless of the operation of this coding contact C15 governing the transmitter relay 4CP. In this way, the conflict in codes or code fight in the track section 4-5T behind a west-bound train is quickly settled and the normal prevailing direction of driven code is established.

When the relay 4CS is dropped away, with the west stick relay 3S picked up, the relay 4CP becomes active for the transmission of an inverse code from left to right in the track section 4-5T by the energization of a circuit each time the track relay 4TR is deenergized extending from the left-hand terminal of the secondary winding of the transformer 4TF including front contact 152 of relay 3S, back contact 73 of relay 4CS, and winding of relay 4CP, to (-).

In accordance with the reception of the inverse code at the right-hand end of the track section 4-5T, the relays 5H, 5HP and 5D (see Fig. 1C) are picked up, and the picking up of the relay 5HP causes the dropping away of the stick relay 5S by opening its stick circuit at back contact 147. The closure of front contact 107 of the

stick relay 5S is no longer essential to the transmission of a driven code from left to right in the track section 6—7T, as a circuit which has been described when considering the normal conditions of the system is closed for the relay 6CP upon the picking up of the relay 5H. Such circuit provides for the transmission of a 180 driven code, thus completing the restoration to normal of the conditions of code transmission in the track section 6—7T.

Although the relay 5D for the right-hand end of the track section 4—5T is picked up under the assumed traffic conditions, it is to be understood that such relay would be deenergized if a train were in approach of the signal 5 because of conditions of code transmission in the track section 4—5T which would be effected by the approach of such train. The control of the signal 5 under conditions involving the passage of following trains will be hereinafter considered with reference to the typical traffic conditions illustrated in Figs. 6A through 6E. It will be noted that although the relay 5D is picked up under the conditions which have been described, the lamps of signal 5 are dark if there is no west-bound train in approach of the signal because of the opening of back contact 75 of the relay 6HP which is picked up in accordance with the reception of an inverse code at the left-hand end of the track section 6—7T.

At the left-hand end of the track section 4—5T, the reception of the 180 driven code causes the relays 4H, 4HP and 4D to be picked up. The green lamp of signal 4 is illuminated under such conditions in accordance with the closure of back contact 70 of the relay 3HP, such relay being deenergized because of the presence of the west-bound train in the track section 2—3T.

The entrance of the west-bound train into the track section 2—3T, in shunting the track section so as to cause the relays 2H and 2HP (see Fig. 1A) to be dropped away, renders the code transmitter relay 1CP inactive for the transmission of a driven code from right to left in the track section 8—1T (Fig. 1D placed to the left of Fig. 1A) by the opening of front contact 49. Upon the removal of such driven code, the dropping away of the relay 8H (see Fig. 1D) at the left-hand end of the track section 8—1T opens the circuit by which the relay 8CP has been active for the transmission of an inverse code, and the closure of back contact 58 of relay 8H renders such code transmitter relay active for the transmission of a 180 driven code by the energization of a circuit for each impulse of the oscillator C180 closed from (+), including contact 52 of relay 8TR in its right-hand position, contact 87 of oscillator C180, back contact 88 of relay 1CS, front contact 89 of relay 7HP, back contact 58 of relay 8H, and winding of relay 8CP, to (-).

The reception of the 180 driven code at the right-hand end of the track section 8—1T causes the picking up of the relay 1D (see Fig. 1A), and the opening of back contact 111 of such relay causes the extinguishing of the yellow lamp of signal 1. The green lamp of signal 1 is illuminated upon the closure of an obvious circuit dependent upon the energized condition of the relays 1H and 1D with the relay 2HP dropped away.

When track section 2—3T is occupied by the west-bound train, the code transmitter relay 3CP for the right-hand end of the track section becomes active in accordance with the restoration

of the normal conditions of code transmission in the track section 4—5T. Thus, upon the picking up of the relay 4H, the relay 3CP becomes active for the transmission of a 180 driven code in the rear of the train by the energization of a circuit which has been described when considering the normal conditions of the system. The conditions are thus established by which a code fight will be effective when the track section 2—3T becomes unoccupied in the rear of the train, and the code transmitter for the right-hand end of the track section will be effective to over-rule the code transmitter for the left-hand end thereof by the dropping away of the relay 2CS for the left-hand end of the track section in a manner similar to that which has been described in detail when considering the code fight in the track section 4—5T. The dropping away of the relay 2CS thus renders the code transmitter relay 2CP inactive for the transmission of a driven code, and a circuit which has been described when considering the normal conditions of the system is closed to render that code transmitter relay active for the transmission of an inverse code from left to right in the track section 2—3T. The restoration in the manner which has been described to the normal conditions of code transmission for the track section 2—3T is effective only if the stretch of single track between sidings B and A is unoccupied by a following train.

The passage of the west-bound train into the track section 8—1T for the siding A causes the dropping away of the relays 1H and 1D. The dropping away of relay 1H opens the circuit by which the green lamp of signal 1 has been illuminated at front contact 110, and closes an obvious circuit for the red lamp of such signal. The energization of the red lamp is effective until the track section 2—3T becomes unoccupied in the rear of the train. Then the signal 1 becomes dark because of the restoration of the relay 2HP.

Further progress of the west-bound train will be readily recognized as effecting a mode of operation comparable to that which has been described when considering in detail the conditions affecting the siding section for the siding B and the signals associated therewith and the conditions of code transmission and signal indications for the stretch of single track between the sidings B and A.

Following east-bound trains

The mode of operation of the system for the passage of a following east-bound train is based upon the principles of operation for east-bound trains as they have already been considered, but as has heretofore been pointed out, there is a difference in the conditions of code transmission in the rear of the first train, dependent upon the presence or absence of a following train. For example, upon comparing Figs. 3E and 5A, it will be noted that the caution indication of the signal 6 is dependent upon the presence of the following train. In other words, the normal conditions of code transmission are restored for the end section adjacent the left-hand end of the siding B unless a following train causes a reversal in the direction of driven code transmission through that track section. In such case a 75 driven code is transmitted from right to left, and the signal 6 is obviously put to caution because of the de-energized condition of the relay 6D for the left-hand end of the track section 6—7T.

More specifically, the entrance of the following train into the stretch of single track between the sidings A and B causes a reversal in the direction of driven code transmission in the track section 6—7T in a manner which has been described, but the driven code transmitted from right to left in the track section 6—7T is a 75 code because of the energization of the relay 1CP (see Fig. 1D) for each impulse of the oscillator C175 in accordance with the deenergized condition of the relay 8H which is dropped away because of the presence of the first east-bound train in the siding section 8—1T. The relay 1CP is energized under such conditions by a circuit closed from (+), including contact 80 of relay 7TR in its left-hand position, back contact 97 of relay 8H, contact 153 of oscillator C175, front contact 100 of relay 1CS, and winding of relay 1CP, to (—). At the left-hand end of the track section, the relay 6H (see Fig. 1C) is energized upon the reception of the 75 code, but the relay 6D is dropped away, and thus an obvious circuit is closed for the yellow lamp of signal 6, the lamp of such signal being illuminated in accordance with the deenergized condition of the relay 5HP for the right-hand end of the track section 4—5T.

To consider another traffic condition involving the passage of following trains, assume each of the east-bound trains to advance a block and assume a position as illustrated in Fig. 5B. Under these conditions, a 120 code is transmitted from right to left through the siding section 8—1T in accordance with the energized condition of the east stick relay 2S (see Fig. 1A) for signal 2 in a manner which has been described with reference to traffic conditions as illustrated in Fig. 3F. The reception of the 120 code at the left-hand end of the siding section causes the relay 8DX (see Fig. 1D) which is tuned to the 120 code to be picked up, and the energized condition of that relay is effective to cause the relay 1CP to be active for the transmission of a 180 driven code for the clearing of signal 6, if reversal in the direction of driven code transmission for the track section has been rendered effective because of the entrance of a following east-bound train into the stretch of single track between the sidings A and B.

Under such conditions the relay 1CP is active for the transmission of a 180 driven code because of the energization of a circuit for each impulse of the oscillator C180 closed from (+), including contact 80 of relay 7TR in its left-hand position, front contact 97 of relay 8H, back contact 98 of relay 8D, front contact 154 of relay 8DX, contact 99 of oscillator C180, front contact 100 of relay 1CS, and winding of relay 1CP, to (—). The reception at the left-hand end of the track section 6—7T of a 180 driven code is effective to cause the clearing of signal 6 in a manner which has been described when considering the traffic conditions as illustrated in Fig. 3C.

Although the apparatus associated with the control of signal 8 is conditioned for the caution indication of such signal under the traffic conditions illustrated in Fig. 5B, the yellow lamp of such signal does not become energized until the following east-bound train enters the track section 6—7T so as to cause the dropping away of the relay 7HP for the right-hand end of that track section. Such conditions are illustrated in Fig. 5C, an obvious circuit being closed for the yellow lamp of signal 8 upon the dropping away of the relay 7HP in accordance with the picked

up and dropped away conditions of the relays 8H and 8D respectively.

It is believed to be readily apparent upon reference to the description as it has been set forth upon considering the passage of a single east-bound train how the proper signal indications are provided for a following train under the traffic conditions illustrated in Figs. 5D, 5E and 5F. That is, upon comparing Figs. 5D and 3C, it will be apparent that the conditions of code transmission for signals governing following train movements in the rear of the first train of Fig. 5D correspond with those which are illustrated for similar signals in Fig. 3C and which have been described in detail. It will be noted that the conditions for the signals governing the passage of a following train as illustrated in Fig. 5E are also similar to those conditions which have been described with reference to the Fig. 3D, the principle difference in the conditions of the two figures for the control of the signals for a following train being that the signal 4 is dark under the traffic conditions illustrated in Fig. 3D because of the energized condition of the relay 3HP for the right-hand end of the track section 2—3T, while such signal has its yellow lamp energized when there is a following east-bound train in approach of such signal as illustrated in Fig. 5E. Under such conditions the yellow lamp of the signal 4 is energized because of the closure of back contact 10 (see Fig. 1B) of the relay 3HP.

In a much similar manner the conditions of Fig. 5F can be compared to the conditions of Fig. 3D in that the signal 6 for governing entrance to the block occupied by the first train has its control apparatus conditioned for the display of a stop indication in each case, but the illumination of the red lamp is effective only under the condition illustrated in Fig. 5F where the deenergized condition of the relay 5HP (see Fig. 1C) for the right-hand end of the track section 4—5T provides for the illumination of the red lamp of signal 6 when the relay 6H is dropped away because of the closure of back contact 102 of relay 5HP.

Following west-bound trains

The same general conditions exist for following west-bound trains as for following east-bound trains, namely, that the tendency of the system is to restore to normal in the rear of the first train unless the presence of a following train is effective to establish a direction of driven code transmission in the track sections characteristic of that direction of traffic. To consider traffic conditions involving the passage of west-bound following trains, typical traffic conditions will be described with reference to Figs. 6A through 6E as compared to traffic conditions which have been described with reference to Figs. 4A through 4E for the passage of a single west-bound train.

Upon comparing Figs. 6B and 4E, it will be noted that the entrance of the following west-bound train into the stretch of single track between the sidings B and C in Fig. 6A has been effective to reverse the direction of driven code transmission in the track sections 3—4T and 4—5T as shown in Fig. 4E, and that the code transmitted through the track section 2—3T is a 75 code in accordance with the deenergized condition of the relay 1H for the right-hand end of the track section 8—1T. The 75 code is not transmitted in the track section 2—3T under the traffic conditions which have been described with reference to the Fig. 4E because the transmission

of such 75 code is dependent upon driven code transmission from left to right through the track section 2-3T as established only when a west-bound train has entered the stretch of single track between sidings.

More specifically, the relay 2CP (see Fig. 1A) for the left-hand end of track section 2-3T is active for the transmission of a 75 driven code under the traffic conditions illustrated in Fig. 6B because of the energization for each impulse of the oscillator C75 of a circuit closed from (+), including contact 26 of relay 2TR in its right-hand position, back contact 155 of relay 1H, contact 156 of oscillator C75, front contact 40 of relay 2CS, and winding of relay 2CP, to (-). The reception of the 75 driven code at the right-hand end of track section 2-3T provides for the energization of the relay 3H (see Fig. 1B), but the relay 3D is dropped away, thus closing an obvious circuit for the yellow lamp Y of signal 3.

When each of the west-bound trains advances a block to establish the traffic conditions as illustrated in Fig. 6C in which the siding section 8-1T for the siding B has become unoccupied in the rear of the first train, the driven code transmitted through the track section 2-3T for the control of signal 3 is changed from a 75 code to a 180 code on account of the energization of the relay 1H (see Fig. 1A) for the right-hand end of the track section 2-1T.

Restoration of code communication in the track section 8-1T for the siding B when such track section becomes unoccupied in the rear of the first train is effective in a manner which has been described when considering the traffic conditions as illustrated in Fig. 4F, except that a 75 driven code is transmitted from right to left instead of a 180 code because of the presence of the following train. The restoration of the inverse code transmitted from left to right in the siding section provides for the energization of the relay 1H for the right-hand end of the track section, and the picking up of such relay closes a circuit which has been described when considering the passage of a single west-bound train to render the relay 2CP active for the transmission of a 180 driven code from left to right in the track section 2-3T. The reception at the right-hand end of the track section of the 180 code causes the picking up of the relay 3D, and the picking up of such relay opens the circuit for the yellow lamp of signal 3 and closes the circuit for the green lamp of that signal by the shifting of contact 157 in an obvious manner.

It will be noted in connection with the traffic conditions just described with reference to the Fig. 6C that the presence of the inverse code transmitted from left to right in the track section 8-1T is dependent upon the closure of front contact 158 of the stick relay 1S (see Fig. 1D). If the train occupying the track section 6-7T were proceeding in the opposite direction, the stick relay 1S would not be picked up, and therefore no inverse code would be transmitted as illustrated by the absence of the inverse code direction arrow in Fig. 3D. This condition has more to do with the passage of opposing trains, but it is mentioned at this point in the description in order to point out that the signal 3 can be cleared when the track section 6-7T is occupied by a train only if the direction of the train is west-bound so as to have caused the picking up of the stick relay 1S.

Under the traffic conditions illustrated in Fig. 6D, the following train is assumed to have entered

the track section 2-3T when the siding section 8-1T for the siding B has become unoccupied in the rear of the first train. The entrance of the following train into the track section 2-3T is effective to cause a reversal in the direction of driven code transmission in the siding section, and upon reversal in the direction of driven code transmission in that section the code transmitter relay for the right-hand end of the section is rendered inactive in order to cause the opposing signal 8 to be put to stop. A 75 driven code is transmitted from left to right through the track section 8-1T for the control of signal 1 in accordance with the energized condition of the stick relay 1S. The relay 8CP is energized for each impulse of the oscillator C75 for the transmission of a driven code by a circuit extending from (+), including contact 52 of relay 8TR in its right-hand position, contact 159 of oscillator C75, front contact 160 of relay 1S, back contact 89 of relay 1HP, back contact 58 of relay 8H, and winding of relay 8CP, to (-).

As the first of the west-bound trains proceeds further along the trackway so as to cause the track section 6-7T to become unoccupied in the rear of the train as illustrated in Fig. 6E, the conditions of code transmission through the track section 6-7T are established in a manner which has been described when considering the passage of a single west-bound train and the picking up of the relay 1HP for the right-hand end of the track section is effective to cause a 180 driven code to be transmitted through the siding section from left to right in accordance with the energization of a circuit which has been described for the code transmitter relay 8CP. The reception at the right-hand end of the track section of the 180 code causes the picking up of the relay 1D, and the picking up of such relay causes the clearing of signal 1 in an obvious manner.

Fig. 6F illustrates a traffic condition in which the second of the west-bound trains has entered the track section 8-1T and the track section 2-3T has become unoccupied in the rear of the train. The conditions of restoration of the system for the track sections in the rear of the train is effective in a manner which has been described when considering the passage of a single west-bound train, and the caution indication of signal 1 is provided in a manner which has also been described upon assuming a traffic condition for a single west-bound train as illustrated in Fig. 4B.

Meeting of trains

The foregoing description of the operation of the system for eastbound and westbound movements includes the control of the signals to provide the desired double-distant indications and siding overlap control for trains making a meet at a passing siding; but it will be helpful to consider briefly the operation of the system for such special conditions for the various positions of opposing trains making a meet as illustrated in Figs. 7A to 7F.

Referring to Fig. 7A, in which two opposing trains are shown as having entered into stretches of single track in their movement to make a meet at the passing siding B, the entrance of each of these trains into its single track stretch causes the tumble-down and code reversal operations previously described, together with the energization of the code sending relays 1CS and 2CS at the opposite ends of the passing siding B. The energization of the code sending relay 1CS by the

eastbound train and the opening of its back contact 57 (see Fig. 1D) stops transmission of the inverse code pulses normally existing in the siding track section as shown in Fig. 2, thereby deenergizing the home relay 1H (Fig. 1A) to close its back contact 155 and provide a caution or 75 code east in the track section 2—3T, thereby causing the intermediate signal 3 to give the desired double-distant indication for the westbound train approaching it. The energization of the code sending relay 2CS by the other westbound train and operation of its contact 48 (see Fig. 1A) changes the driven code in the siding section from the 180 code rate normally existing (see Fig. 2) to the 75 code rate as shown in Fig. 7A, thereby releasing the code responsive relays 8D in Fig. 1D, while maintaining energized the home relay 8H. Under these conditions the coding contact C75 is effective to govern the transmitter relay 7CP by the circuit through back contacts 154 and 98 of relays 8DX and 8D and front contact 97 of home relay 8H, thereby providing the caution 75 code rate for the control of the intermediate signal 6 and causing that signal to give the desired double-distant indication for the eastbound train approaching it.

Thus, as the opposing trains in question approach the passing siding B, as indicated in Fig. 7B, each train will get the proper advance warning or double-distant indication at the intermediate signals 3 and 6 which are required for absolute-permissive-block signaling systems for reasons familiar to those skilled in the art.

In connection with this double-distant control, it will be noted that the eastbound train exercises its control past or through the siding section for the desired double-distant indication by cutting off or stopping the inverse code normally existing to put opposing signal 1 to stop and signal 3 to caution; while the westbound train exercises its control past the siding section for the double-distant indication by changing the normal 180 code rate to the 75 code rate.

Considering now the siding overlap control, assume first that the westbound train advances from the position as shown in Fig. 7B into the end track section 2—3T as indicated in Fig. 7F. The entrance of this westbound train into this end track section 2—3T stops the coding operation of the track relay 2TR by the inverse code pulses, thereby deenergizing home relay 2H and its repeater relay 2HP to open the front contact 49 of that relay (Fig. 1A) to stop transmission of driven code in track section 8—1T toward the opposing signal 8, thereby providing the desired overlap control of this signal 8.

Upon entrance of the westbound train into the end track section 2—3T, and the cessation of the driven code in a normal prevailing direction in the siding section, the resultant deenergization of the home relay 8H in Fig. 1D closes its back contact 58 to connect transmitter relay 8CP to coding contacts as selected by the existing condition of relays 7HP and 7CS. In the case assumed, the presence of the eastbound train and resultant energization of the code sending relay 7CS renders the coding contacts C75 effective to govern the energization of the transmitter relay 8CP, thereby causing the signal 1 to give a caution indication, as indicated in Fig. 7F.

When the eastbound train enters the end track section 6—7T as indicated in Fig. 7C, the coding operation of the track relay 7TR by inverse code pulses is stopped to release home relay 1H and its repeater relay 1HP (Fig. 1D); but in this

case there is no change in the coding at that time, because the opposing signal 1 is already at stop. The release of the repeater relay 1HP, however, opens its front contact 89, so that if a westbound train should enter the end track section 2—3 and tend to cause the same reversal in direction of code in the siding section as indicated in Figs. 4C and 7F to clear the signal 1, the deenergization of the relay 4HP by the presence of the eastbound train would prevent any such coding and the signal 1 would remain at stop, as shown in Fig. 7D.

It is therefore believed to be obvious from the typical conditions that have been described how single block overlap control is provided for the entering signals at a siding in such a manner as to be positive in its operation irrespective of the sequence of approach to the siding of opposing trains.

With reference to Fig. 7E, it has been assumed that the westbound train has entered the siding for the meeting of the two trains. The leaving signal 2 clears for the eastbound train under such traffic conditions in accordance with the usual mode of operation for restoration to normal conditions in the rear of a westbound train. A similar condition exists with the clearing of the leaving signal 7 in the rear of the eastbound train. Thus, the conditions are established whereby the eastbound train can proceed into the stretch of single track between the sidings B and C, and whereby the westbound train can proceed into the stretch of track between the sidings A and B.

Outlying switch

Inasmuch as it is often required in practice that the system be adapted to provide for signaling past an outlying switch, the single switch 2W has been illustrated in Fig. 1B as connecting a spur track to the main track at track section 4—5T. With the track switch in its normal position, the closure of contact 66 of the switch circuit controller in the track circuit for the track section provides for the control of the signals as if there were no switch in the stretch of single track between the sidings.

The use of an outlying switch in practice generally requires that a train be permitted to enter the spur track either to leave cars or to get into the clear for a train on the main line, and then to proceed under dispatcher's orders in either direction on the main track. In either case it is generally required that the trainmen restore the outlying switch to its normal position after the train has entered the spur track, and then obtain instructions from the dispatcher prior to moving out again onto the main line. It is therefore required that the system be adapted so as to restore properly after a train has entered the spur track and the outlying switch has been restored to its normal position, and it is also required that the system be operative to provide proper signaling protection upon the passage of a train in either direction after leaving the spur track in accordance with the instructions received by trainmen upon communication with the dispatcher.

It is believed to be readily apparent that the mode of operation of the system upon the entrance of a train into the spur track connected by the track switch 2W to the track section 4—5T from either direction involves the same mode of operation of the system that has been described for such respective direction of train movement. In other words, the conditions which exist upon

the entrance of a train into the stretch of track after the track switch 2W has been operated to its reverse position has no affect upon the system other than the affect of occupancy of the train of the particular track section involved. Such being the case, the conditions of code transmission which exist upon the entrance of a west-bound train into the spur track connected to the track section 4—5T by the track switch 2W correspond to the conditions of code transmission illustrated in Fig. 4B where the west-bound train is assumed to occupy the track section 4—5T. In a similar manner, if the train involved is an east-bound train, the conditions of code transmission which exist upon the backing of a train into the spur track connected by the track switch 2W to the track section 4—5T correspond with the conditions of code transmission as illustrated in Fig. 3C.

When the track switch 2W is restored to its normal position, after a west-bound train has proceeded into the spur track, the closure of contact 66 of the switch circuit controller for the track switch 2W provides for the energization of the track circuit for the track section 4—5T just as if the track section had become unoccupied in the rear of a west-bound train under the conditions which have been described. The conditions of code transmission are therefore restored for the track section 4—5T as illustrated in Fig. 4D where that track section has become unoccupied in the rear of a west-bound train.

The reception at the left-hand end of the track section 4—5T of a 180 driven code under the conditions where a west-bound train has entered the spur track, causes the code transmitter for the right-hand end of the track section 2—3T to become active in a manner which has been described under the traffic conditions illustrated in Fig. 4D. After such code transmitter has become active, a code fight is effective for the transmitters for the opposite ends of the track section, and the transmitter for the right-hand end of the track section is effective to overrule the transmitter for the left-hand end so as to cause a restoration to normal of the conditions of code transmission in the track section 2—3T. Thus, the conditions of code transmission are restored to normal for each of the track sections in the stretch of single track with which the spur track and single track switch 2W is associated.

It is believed that it should be readily apparent from the diagrams of Fig. 3C and Fig. 3D for east-bound traffic that a similar mode of operation is effective if the train entering the spur track is an east-bound train to cause restoration to normal for the conditions of code transmission for the track sections of the stretch of single track with which the spur track and track switch 2W are associated.

After considering with reference to Fig. 4A the conditions upon passage of a west-bound train which are effective for causing a reversal in the direction of driven code transmission for the track section 2—3T for the left-hand end of a stretch of single track between sidings, it will be apparent that the removal of the code transmitted from right to left in the track section 4—5T was instrumental in causing the reversal in the direction of driven code transmission in the track section 2—3T. Such being the case, the removal of the code from the track section 4—5T by the reversal of the track switch 2W is effective to cause a reversal in the direction of driven code trans-

mission in the track section 2—3T. It has also been pointed out that the entrance of an east-bound train into the stretch of single track between sidings causes a reversal in the direction of driven code transmission in the track section 6—7T because of the removal of the inverse code normally transmitted from left to right in the track section 4—5T. Thus, the reversal of the track switch 2W, upon removing the code from the track section 4—5T, causes a reversal in the direction of driven code transmission for the track section 6—7T so as to cause the signal 6 for governing east-bound traffic to be controlled in accordance with the reception of a driven code.

The reversal of the track switch 2W for the passage of a train from the spur track onto the main track is therefore effective to cause the transmission of a driven code from left to right in the track section 2—3T for the control of signal 3, and also to cause the transmission of a driven code from right to left in the track section 6—7T for the control of signal 6. In this manner the system is conditioned so that the train can proceed in either direction, in accordance with the instructions received from the dispatcher, under conditions where safe signaling protection is involved. It will be noted that the train under such conditions would have adequate opposing train protection irrespective of the direction in which it proceeded because the restoration to normal of the conditions as they have been described prior to movement of the train out of the spur track causes the restoration to normal of all stick relays that could have been picked up in the rear of the train when it first entered the track section 4—5T.

Having described a block signaling system for a particular stretch of single track as one specific embodiment of the present invention, it is desired to be understood that this form is selected to facilitate in the disclosure of the invention rather than to limit the number of forms which the invention may assume, and it is to be further understood that various adaptations, alterations and modifications may be applied to the specific form shown to meet the requirements of practice without in any manner departing from the spirit or scope of the present invention except as limited by the pending claims.

What I claim is:

1. In a coded track circuit signaling system for single track railroads, a stretch of single track between passing sidings including an end track section adjacent each siding, means for normally transmitting over the track rails of each end section a driven code toward the corresponding siding and an associated inverse code in the opposite direction, code sending means for each section automatically rendered effective by cessation of the normal driven code in that section for transmitting a reverse driven code in that section, means for providing an inverse code in each end section upon reversal of the prevailing direction of driven code therein, means for maintaining each code sending means effective regardless of the presence of an inverse code until the normal driven code is restored, a head block signal at each end of each stretch for governing traffic into the stretch, and decoding means responsive to either a driven or an inverse code in an end section transmitted toward the corresponding head block signal for governing the indications thereof only if the corresponding code sending means is not effective, and for detecting occupancy of the corresponding end section by a

train approaching the corresponding head block signal.

2. In a coded track circuit signaling system for single track railroads, a stretch of single track between passing sidings divided into track sections, a head block signal at each end of the stretch for governing train movement into the stretch, intermediate signals at intervals in said stretch for governing traffic in opposite directions through the stretch, means for normally transmitting over the track rails of each track section a driven code in a prevailing direction and an associated inverse code in the opposite direction, the prevailing direction of driven code in each end track section of the stretch adjacent a siding being toward that siding, means responsive to the entrance of a train at either end of the stretch for cutting off transmission of a code toward the other end of the stretch in each track section to put to stop the opposing signals, means responsive to the cessation of the normal driven code in each section for automatically transmitting a reverse driven code in that section for clearing an intermediate signal, means effective upon reversal of the normal driven code in an end section for providing an inverse code in that section, decoding means responsive to either a driven code or an inverse code in an end section transmitted toward the corresponding siding, and means for rendering said decoding means effective to clear the corresponding head block signal only if said decoding means is being operated by a driven code, whereby said decoding means may be operated by an inverse code while the corresponding head block signal is held at stop to block opposing train movements until an approaching train enters the corresponding end track section.

3. In a coded track circuit system for single track railroads, a stretch of track between passing sidings divided into a plurality of track sections, signals at intervals for governing traffic in opposite directions into and through said stretch, means normally acting to transmit over the track rails of each track section a driven code in a predetermined prevailing direction and an inverse code in the opposite direction, the prevailing direction of the normal driven code in each end section of the stretch adjacent the siding being toward the corresponding siding, means associated with the adjoining ends of adjacent sections and responsive to coding in one section for governing the coding in the adjacent section, whereby the entrance of a train into said stretch at either end stops transmission of coding toward the other end in each section to put to stop all opposing signals, means responsive to the cessation of the normal driven code in each section for transmitting a reverse driven code in that section to clear an intermediate signal, means effective upon reversal of the prevailing direction of driven code in an end section for providing an inverse code in that section, and means for each end of the stretch including decoding means responsive to either a driven or an inverse code transmitted toward that end of the stretch for governing the proceed indications of the corresponding head block signal in accordance with the normal driven code only and for detecting occupancy of the corresponding end section by a train approaching a head block signal while that signal is held at stop.

4. In a system for governing the indications of signals for single track railroads by coded track circuits without line wires, a stretch of single

track between passing sidings including an end track section at each end and an intermediate track section, intermediate signals at the ends of said intermediate section for governing traffic in opposite directions, means normally acting to transmit over the track rails of each track section a driven code in a predetermined prevailing direction and an associated inverse code in the opposite direction, the prevailing direction of the normal driven code in each end section being toward the corresponding siding, means associated with the adjoining ends of adjacent track sections and responsive to the transmission of a code toward such end of either section for governing the transmission of coding from such end of the adjacent section, means responsive to the cessation of the normal driven code in each section for automatically transmitting a reverse driven code in that section for clearing an intermediate signal, means effective upon reversal of the normal driven code in each end section for providing an inverse code in that section independently of the occupancy of other sections to detect occupancy of that end section by a train approaching the corresponding siding, decoding means for each end of the stretch responsive to the transmission of either a driven code or an inverse code toward the corresponding end, and a head block signal at each end of the stretch governing traffic into the stretch and cleared by operation of said decoding means in response to the normal driven code only.

5. In a system of the character described for governing the indications of single track railroads by coded track circuits and without line wires, a stretch of single track between passing sidings including an end track section at each end and an intermediate section, intermediate signals one at each end of the intermediate track section governing traffic in opposite directions, means associated with each track section for normally transmitting over the track rails thereof a driven code and an associated inverse code, means for rendering the normal code in each section dependent upon coding in the same direction in an adjoining section, the prevailing direction of said normal driven code in each end track section being toward the corresponding siding, code reversing means responsive to the cessation of the normal driven code in each track section for automatically transmitting a reverse driven code in that section for clearing an intermediate signal, said code reversing means being maintained effective until the normal driven code in the corresponding section is restored, a directional stick relay for each intermediate signal energized by a train moving in the direction of traffic governed thereby for providing a driven code in the track section in the rear for following train movements, means effective upon reversal of the normal direction of driven code in an end section for providing an inverse code in that section toward the corresponding siding, a head block signal at each end of the stretch governing traffic into the stretch, and means responsive to a driven code but not to an inverse code transmitted toward the head block signal for clearing that signal.

6. A coded track circuit signal system for single track railroads comprising, an end track section of a stretch of single track adjacent a passing siding and having a head block signal at one end governing train movement into said stretch, means for normally transmitting over the track rails of said end section a driven code

toward said head block signal for governing the indications thereof after a train has moved through the stretch in either direction, means responsive to the cessation of said normal driven code for transmitting a driven code in the opposite direction and providing a reverse inverse code in that section tending to govern said head-block signal the same as said driven code, said means when effective preventing clearing of said head block signal, and signaling means governed by said reverse inverse code and responsive to the occupancy of said end section by a train moving toward the head block signal while that signal is held at stop.

7. In a coded track circuit signaling system for single track railroads, a stretch of single track between passing sidings divided into track sections, a head block signal at each end of the stretch governing train movement into the stretch, intermediate signals at intervals for governing train movement in opposite directions through the stretch, means for normally transmitting a driven code and an associated inverse code in each of said track sections, the normal prevailing direction of the driven code in the end sections of the stretch being toward the corresponding siding, a code sending relay associated with each head block signal, means for energizing each code sending relay upon cessation of the driven code in the prevailing direction in the corresponding end section, means effective when a code sending relay is energized for supplying a reverse driven code to the siding end of said end section for clearing an intermediate signal, and means for holding at stop each head block signal when its corresponding code sending relay is energized.

8. A coded track circuit signal system for single track railroads comprising, an end track section of a stretch of single track adjacent a passing siding having a head block signal at one end governing train movement into said stretch and an intermediate signal at the other end governing train movement toward the siding, means for normally transmitting over the track rails of said end section a driven code toward said head block signal, means responsive to the presence of a train in the stretch moving toward the siding for cutting off said normal driven code, a code sending relay energized by the cessation of said normal driven code for transmitting a reverse driven code in the opposite direction for controlling the indications of said intermediate signal, means associated with said intermediate signal for providing inverse code pulses in said end section during the off periods of the reverse driven code therein, a track relay for the siding end of said end sections, means including said track relay for maintaining said code sending relay energized while said track relay is being operated by said inverse code pulses and for automatically deenergizing said code sending relay when said track relay is energized longer than an off interval of the reverse driven code, and decoding means governed by said track relay and effective to clear said head block signal only if said code sending relay is deenergized.

9. In a coded track circuit signal system for single track railroads, a stretch of single track between passing sidings, a track relay connected across the track rails at each end of said stretch, a code transmitter and a code sending relay associated with each end of said stretch, each code sending relay when energized rendering the

associated code transmitter effective to supply driven code pulses to the corresponding end of said stretch only if said corresponding track relay is deenergized for each code pulse, two independent stick circuits for maintaining each code sending relay energized, one stick circuit including a back contact of the corresponding track relay, the other stick circuit including back contacts of the corresponding code transmitter closed during the off intervals of the driven code, decoding means associated with each track relay and responsive to its coded operation, and a head block signal at each end of said stretch governing traffic into the stretch and having its indications governed by the corresponding decoding means only if the corresponding code sending relay is deenergized.

10. In a signal system for single track railroads, an end track section of a stretch of single track adjacent a passing siding, a track relay and a code transmitter relay for the siding end of said track section, a code transmitter, a code sending relay acting when energized to render said code transmitter effective to energize said code transmitting relay only if said track relay is deenergized at the beginning of each on period of the code provided by said transmitter, said code transmitter having back contacts closed during the off period of the driven code, and two independent stick circuits for said code sending relay, one stick circuit including a back contact of said track relay, the other stick circuit including said back contacts of said code transmitter, whereby said code sending relay is maintained energized even though said track relay is operated by inverse code pulses but is automatically deenergized if said track relay is energized longer than the off period of the driven code.

11. In a coded track circuit signal system for single track railroads, a stretch of single track between passing sidings having intermediate signals at intervals for governing traffic in opposite directions, a code sending relay for each end of said stretch effective when energized to supply a driven code to the corresponding end of the stretch for governing intermediate signals, means for energizing each code sending relay for the movement of trains toward the corresponding end of said stretch, means effective only if said stretch is not occupied by a train for deenergizing said code sending relay automatically after energization thereof, decoding means associated with each head block signal and responsive to codes transmitted toward that signal, and means controlled by each decoding means for governing the indications of the corresponding head block signal only if its corresponding code sending relay is deenergized.

12. In a coded track circuit signaling system for single track railroads, the combination with a stretch of single track connecting with a passing siding and having an end section adjacent the siding, of a code sending relay acting when energized to transmit over the track rails of said end section a driven code away from the siding, means acting upon the entrance of a train into said stretch at the end remote from said siding to cause energization of said code sending relay, decoding means associated with the siding end of said end section, means for applying current pulses to the track rails of said end section at the end remote from the siding of a character to energize said decoding means while leaving said code sending relay energized, and means

effective when said single track stretch becomes unoccupied for applying current pulses of a different character to the track rails at said remote end of said end section to cause automatic de-energization of said code sending relay.

13. In a coded track circuit signal system for single track railroads, a siding track section opposite a passing siding and an end section of a stretch of single track extending in one direction from said siding section, a head block signal at the siding end of said end section for governing train movement into the stretch of single track, an entering signal at the other end of the siding section governing train movement in the same direction, means for transmitting over the track rails of said end section toward said head block signal a driven code under certain conditions and an inverse code under other conditions, means associated with said head block signal for clearing it in response to said driven code but not the inverse code, and means responsive to the presence of said codes of either kind in said end section for governing the clearing of said entering signal by means of code transmitted over the track rails of the siding section, said means acting to cause said entering signal to indicate stop when a train in the stretch of single track approaching said siding and holding said head block signal at stop enters said end section and stops the transmission of all code toward said head-block signal.

14. In a coded track circuit signal system for single track railroads, the combination with a siding section of track adjacent a passing siding and stretches of single track extending in opposite directions from said siding section to other sidings, an entering signal at each end of said siding section and an intermediate signal in the rear thereof for governing traffic in the same direction toward and into said siding section, a head block signal at each end of each single track stretch for governing traffic in opposite directions into that stretch, means for normally transmitting driven and inverse codes over the track rails of said single track stretch for clearing the head block signals at both ends thereof, coding means for the siding section including track relays and code transmitting means for transmitting over the track rails of said section at different times driven codes of different rates in opposite directions and an inverse code associated with said driven codes in one direction only, and means associated with each end of said siding section and responsive to the presence and location of a train in the corresponding stretch of single track and approaching said siding section for governing the codes transmitted by said siding coding means to cause the opposing intermediate signal to indicate caution when the train enters said stretch and thereby cause said intermediate signal to give a double distant caution indication, said means being responsive to the movement of such train into the end track section beyond the intermediate signal for said stretch to cause the opposing entering signal to indicate stop and thereby provide a siding overlap control.

15. A system for governing by coded track circuits and without line wires train movements at a passing siding of a single track railroad comprising, a siding section opposite a passing siding and end track sections of the stretches of single track connecting with the ends of said siding section, a head block signal adjacent each end of the siding section for governing train

movement from the siding into the adjoining stretch of single track, an entering signal at each end of said siding section for governing train movement into that section, an intermediate signal in the rear of each entering signal, means for normally transmitting over the track rails a driven code in a prevailing direction and an inverse code in the opposite direction for each of said track sections, said prevailing direction of driven code in each end section being toward the siding, code reversing means responsive to the cessation of the driven code in the prevailing direction in each end section for automatically reversing the direction of driven codes in that section for clearing the intermediate signal and also providing a reverse inverse code in that section only for detecting occupancy thereof by an approaching train, said code reversing means for one of said end sections acting to change the rate of the normal driven code through the siding section to cause the opposing entering signal and associated intermediate signals to give a double distant indication, said code reversing means for the other end section cutting off the normal inverse code in the siding section to cause the opposing intermediate signal to give a double distant indication, means responsive to the cessation of the reverse inverse code in each end section upon occupancy of that section by a train approaching the siding for preventing transmission of a driven code through the siding section toward the other end section, and means responding to the cessation of the driven code in the prevailing direction in said siding section for automatically reversing the direction of the driven code therein.

16. In a coded track circuit signaling system for single track railroads, the combination with a siding section of track adjacent a passing siding and stretches of single track extending in opposite directions therefrom to other sidings, each of said stretches including an end section adjacent said siding section, an entering signal at each end of said siding section governing traffic into said section, a head-block signal at each end of each stretch of single track for governing traffic in opposite directions into that stretch, means normally acting to provide code pulses in each stretch of single track for clearing the head-block signals at both ends thereof, means normally acting to provide code pulses in opposite directions over the track rails of said siding section, means responsive to the entrance of a train into one single track stretch for stopping transmission of code pulses in said siding section toward the opposing entering signal, and means effective when a train approaching said siding section in the other single track stretch has advanced into the corresponding end track section for stopping transmission of code pulses in said siding section toward the opposing entering signal.

17. A system of signaling for single track railroads employing coded track circuits and comprising, a siding track section opposite a passing siding and a stretch of single track extending from each end thereof to an adjacent siding, each of said stretches of single track having an end track section adjacent said siding section, a head block signal at each end of the siding section governing train movement into the corresponding stretch of single track, means associated with each stretch of single track and normally acting when that stretch is not occupied by a train for transmitting a driven code toward said siding section for governing the indications of

the corresponding head block signal, said means acting upon the entrance of a train into the corresponding stretch for reversing the direction of driven code in the end section to put the opposing head block signal to stop while maintaining an inverse code in said end section to detect its occupancy by a train, an entering signal at each end of said siding section for governing train movement into that section, and means responsive to the cessation of the inverse code in the end section toward the siding when a train approaching said siding enters said end section for causing the opposing entering signal to indicate stop.

18. A coded track circuit system for governing the indications of entering signals for passing sidings on single track railroads without line wires comprising, a siding track section opposite a passing siding and end track sections of stretches of single track connecting with the ends of said siding section, an entering signal at each end of said siding section governing train movement into that section, means for transmitting over the track rails a driven code in a prevailing direction in each of said track sections and an inverse code in the opposite direction, the normal prevailing direction of the driven code in each end section being toward the siding, means responsive to the cessation of the normal driven code in each end section for automatically reversing the direction of driven code in that section and providing an inverse code toward the siding in that section only, and means responsive to the presence of either a driven or an inverse code in each end section for governing the indication of the opposing entering signal by means of the code transmitted over the track rails of said siding section, and thereby provide a siding overlap control for said entering signals without line wires.

19. A system for governing by coded track circuits and without line wires train movements at a passing siding of a single track railroad comprising, a siding track section opposite a passing siding and end track sections of the adjoining stretches of single track connecting with the ends of said siding section, an entering signal at each end of said siding section for governing train movements into that section, means for transmitting a driven code over the track rails of the siding section in a predetermined prevailing direction and an inverse code in the opposite direction, means responsive to the cessation of the normal driven code in said siding section for transmitting a driven code in the opposite direction, means responsive to the presence of a train in each end section for cutting off any transmission of code in the siding section toward the other end section, means for governing the code rate of the normal and reverse driven codes in said siding section by a train approaching the siding in the direction of such driven code, and de-coding means for governing the indications of each entering signal in accordance with the rate and existence of the driven code transmitted toward that signal.

20. In a coded track circuit system of automatic block signaling for single track railroads including a siding track section adjacent a passing siding with stretches of single track extending in opposite directions therefrom to other sidings, each single track stretch having an end track section adjacent the siding, an entering signal at each end of said siding section for governing train movement into that section, means

for at times transmitting a code in one direction over the track rails of said siding section for governing the indications of one entering signal and at other times transmitting a code in the opposite direction for governing the indications of the other entering signal, and means responsive to the presence of a train in either one of said end track sections of the stretches of single track and effective regardless of other trains if said train is approaching the siding but not if it is moving in the opposite direction for preventing transmission of a code over said siding section toward the other end and thereby cause the opposing entering signal to indicate stop.

15 21. In a coded track circuit automatic block signal system for single track railroads including a siding track section adjacent a passing siding and a stretch of single track extending in one direction from said siding section, said single track stretch including an end track section adjacent the siding section, an entering signal for governing traffic from said single track stretch in said siding section, means normally acting to transmit a driven code over the track rails of 20 said siding section in the direction of traffic governed by said entering signal, means responsive to the cessation of said normal driven code for transmitting reverse driven codes in the opposite direction over the track rails of said siding section for governing the indications of said entering signal; and means responsive to the presence of a train in said end track section of the stretch of single track and effective if said train is moving toward the siding section but not if moving 25 in the opposite direction for cutting off said normal driven code and thereby automatically reverse the direction of coding in the siding section to govern the indications of said entering signal.

40 22. In a coded track circuit automatic block signal system for single track railroads including a siding section adjacent a passing siding and stretches of single track extending in opposite directions from said siding section, each single track stretch including an end track section adjacent the siding, an entering signal at each end of the siding section for governing train movement into that section from the corresponding single track stretch, means normally transmitting a driven code over the track rails of said siding section in one direction for governing the indications of one of said entering signals, means responsive to the cessation of said normal driven code for transmitting a reverse driven code in the opposite direction over the track rails of said siding section for governing the indications of the other entering signal, means responsive to the presence of a train in the end track section of one of said stretches of single track adjacent said other entering signal for cutting off said normal driven code to put the opposing entering signal to stop and create a reverse driven code in said siding section for governing said other entering signal, and means responsive to the presence of a train in the other end track section adjacent said first mentioned entering signal for preventing transmission of any reverse driven code in the siding section.

70 23. In a coded track circuit signaling system for single track railroads having a siding track section adjacent a passing siding and a stretch of single track extending in each direction from said siding section, an entering signal and an intermediate signal in the rear thereof for governing the movement of trains in one of said

stretches of single track toward and into said siding section, means for normally transmitting over the track rails of said siding section a driven code in the direction of traffic governed by said signals and an associated inverse code in the opposite direction, means for governing the clear and caution indications of said intermediate signal in accordance with the presence or absence of said inverse code, and means responsive to the presence of a train in the other stretch of single track if such train is approaching the siding section but not if it is moving away from that section for cutting off said inverse code to cause said intermediate signal to give a double distant caution indication.

24. In a coded track circuit system for single track railroads having a siding track section adjacent a passing siding and a stretch of single track divided into track sections and connecting with each end of said siding section, an entering signal and an intermediate signal in the rear thereof for governing train movement in each stretch toward and over the siding section, means for transmitting over the track rails of each track section a driven code in one prevailing direction and an inverse code in the opposite direction, means responsive to the entrance of a train into one stretch of single track for changing the code rate of the normal driven code in the siding section to cause the entering signal and intermediate signal for opposing train movements to give a double distant indication, means for cutting off said normal driven code in said siding section when said train enters the end section adjacent the siding to put to stop the opposing entering signal, and means responsive to such cessation of the normal driven code in the siding section for transmitting a driven code through that section in the opposite direction at a rate determined by traffic conditions in the other stretch.

25. In a coded track circuit signaling system for single track railroads, the combination with a track section and means for transmitting distinctive codes over the track rails of said section in one direction for giving signal indications to control train movement, of decoding means energized in response to any one of said codes, a directional stick relay, and means including contacts closed temporarily only when said decoding means is first deenergized and means operated only by the presence of a train in said track section adjacent the code receiving end for temporarily energizing said stick relay, and a stick circuit for said stick relay maintained closed so long as said decoding means is deenergized, whereby the directional stick relay is automatically energized and maintained energized by a train entering said track section in a direction opposite to the direction of the code transmitted over the track rails of said track section.

26. In a coded track circuit signaling system for single track railroads, the combination of a track section, a signal at one end of said track section governing train movements into that section, means for transmitting over the track rails of said track section driven codes of different code rates toward said signal for governing its indications, decoding means responsive to said driven codes, a source of current, a series relay, a directional stick relay having its pick-up circuit including a front contact of said series relay, means responsive to the deenergization of said decoding means for temporarily connecting said series relay and source of current across the

track rails at the end of said track section adjacent the signal and for also supplying current to said pick-up circuit for a limited time, said series relay being energized only by a wheel shunt adjacent the signal, and a stick circuit for said directional stick relay maintained closed so long as said decoding means is deenergized.

27. In a coded track circuit signal system for single track railroads, a source of current, a track relay, a transmitter relay for connecting said source of current and said track relay across the track rails of a track section alternately as said transmitter relay is energized and deenergized, a series relay included in series with said source of current and energized only by a wheel shunt, decoding means including a signal control relay governed by the operation of said track relay, a slow-release repeater relay released after a time following deenergization of said signal control relay, a directional stick relay, a pick-up circuit for said directional stick relay including front contact of said series relay, a front contact of said repeater relay and a back contact of said signal control relay, and means for temporarily energizing said transmitter relay upon release of said signal control relay.

28. In a coded track circuit signal system for single track railroads, a signal at one end of a track section governing train movements into said section, a signal control relay responsive to the transmission of a code in said section toward said signal for governing its indications, a source of current, a series relay, means responsive to the deenergization of said signal control relay for temporarily connecting said source of current and series relay across the track rails at said end of said section, said series relay being energized only by a wheel shunt, a slow-release repeater relay deenergized after a time upon deenergization of said signal control relay, a directional stick relay, and a pick-up circuit for said stick relay including front contact of said series relay, a front contact of said slow-release repeater and a back contact of said signal control relay, whereby said directional stick relay is energized by a train travelling in the direction of traffic governed by said signal but not by a train travelling in the opposite direction.

29. In a coded track circuit signal system for single track railroads, a stretch of single track between passing sidings divided into track sections, coded track circuit means for each track section operable normally when that section is not occupied by a train to transmit a driven code in a predetermined prevailing direction in the corresponding track section, a code responsive relay for the end of each track section receiving a driven code in the prevailing direction, code reversing means responsive to the deenergization of said code responsive relay upon cessation of the driven code in the prevailing direction for initiating transmission of a driven code in the opposite direction until the prevailing direction of driven code is restored, a directional stick relay associated with each code reversing means and energized by a train moving in the opposite direction to the prevailing direction of driven code in the corresponding track section, said directional stick relay being maintained energized so long as the corresponding code responsive relay is deenergized, and means effective when a given directional stick relay is energized for preventing transmission of a reverse driven code in the corresponding section, whereby a driven code in the reverse direction does not follow up a train mov-

ing through a track section and interfere with the restoration of the driven code in the prevailing direction when that section is vacated by said train.

30. In a coded track circuit signaling system for single track railroads, an insulated section of a stretch of single track, signals for governing traffic in opposite directions over said section, means normally acting to transmit a driven code in a predetermined prevailing direction over the track rails of said section for governing the indications of one of said signals, code reversing means responsive to the cessation of said normal driven code for transmitting a reverse driven code in the opposite direction for governing the indications of the other signal, said code reversing means being restored to normal by said normal driven code, and means rendered effective by the presence of a train in said section only if that train entered said section in the direction of said reverse driven code for preventing transmission of that reverse driven code behind a train while said section is occupied and until after a normal driven code has been restored.

31. In a coded track circuit automatic block signal system for single track railroads, an insulated section of a stretch of single track, signals for governing traffic in opposite directions over said section, a track relay for each end of said section, code transmitting means associated with each end of said section for at times transmitting over the track rails thereof a series of driven code pulses for governing the indications of the signal at the other end of said section, and circuit means for rendering said code transmitting means effective to apply a code pulse only if the corresponding track relay is deenergized at the time such code pulse should be initiated.

32. In a coded track circuit signaling system for railroads, in combination with an insulated track section, of code transmitting and receiving means associated with each end of said track section and comprising a source of current, a track relay, a code transmitting relay, a code transmitter, and a code responsive relay energized by the coded operation of said track relay, said code transmitting relay acting when energized and deenergized to alternately connect said source of current and said track relay across the track rails at the corresponding end of said track section, said code transmitter at the opposite ends of said track section having contacts closed periodically at substantially the same code rate but at slightly different time intervals so as to change their time phase relation within a limited time, and circuit means for connecting each code transmitting relay with the contacts of its associated code transmitter to apply driven code pulses to the corresponding end of said track section, said circuit means for one end of said track section being effective only if the corresponding track relay and code responsive relay are deenergized, whereby code pulses received at said one end will automatically stop transmission of the driven code from that end when driven codes are applied concurrently to both ends of said track section.

33. In a coded track circuit signaling system for railroads, an insulated track section between opposing signals governing traffic in opposite directions, code transmitting and receiving means associated with each end of said track section and including a track relay, a code transmitter, and a code responsive relay energized by the coded operation of said track relay, code reversing means associated with one end of said section and in-

cluding a stick relay acting when energized to render the associated code transmitter effective to apply driven code pulses across the track rails of said track section at said one end, a pick-up

5 circuit for said stick relay temporarily closed upon deenergization of the corresponding code responsive relay, and a stick circuit for said stick relay closed while the corresponding track relay is deenergized, whereby transmission of a current 10 pulse toward said one end of said track section automatically stops transmission of a reverse driven code in the opposite direction by deenergizing said stick relay.

34. In a coded track signaling system for single track railroads, in combination with an insulated 15 track section between opposing signals governing traffic in opposite directions, code transmitting and receiving means associated with each end of said track section and including a track relay, a code responsive relay energized by the coded operation of said track relay, and a code transmitter; a directional stick relay for each end of said section automatically energized and maintained energized while said section is occupied by a train only if that train entered said section from the corresponding end, a code reversing stick relay associated with one end of said section and acting when energized to render the associated code transmitter effective to apply driven code pulses to the track rails at said one end of said track section, means effective only if the corresponding directional stick relay is deenergized for energizing said code reversing stick relay upon deenergization of the corresponding code responsive relay and maintaining it energized until the associated track relay is energized, and circuit means for rendering the code transmitter for the other end of said track section effective to supply code pulses to the track rails only if the corresponding directional stick relay is deenergized and the corresponding track relay is deenergized at the time each pulse is to be supplied.

35. In a coded track circuit signaling system for single track railroads, the combination with 45 a track section, of means for each end of said track section including a source of current, a code following track relay, a transmitter relay and coding contacts operated intermittently at recurrent intervals, each transmitter relay acting when energized and deenergized respectively to connect said source of current and said track relay alternately across the track rails at the corresponding end of said track section, an energizing circuit for each transmitter relay including the associated coding contacts and a back contact of the corresponding track relay, a signal at each end of said track section for governing train movements over said track section, and decoding means associated with each signal for governing its indications in accordance with the coding operation of its corresponding track relay.

36. In a coded track circuit signaling system for single track railroads, a stretch of single track between passing sidings and including an end track 50 section at each end, a headblock signal at each end of the stretch for governing train movement into the stretch, intermediate signals at the ends of said end track sections for governing train movement towards the ends of the stretch, code transmitting means including intermittently operated coding contacts and normally acting to transmit driven code pulses over the track rails of each end track section toward the corresponding head-block signal, means responsive to the entrance of a train at either end of said stretch

for stopping transmission of the normal driven code pulses toward the opposing head-block signal, and means responsive to the cessation of the normal driven code pulses being received at either head-block signal for causing transmission of reverse driven code pulses and thereby govern the indications of the intermediate signal for the corresponding end section.

37. In a coded track circuit signaling system for a stretch of single track including an end track section at each end, a head-block signal at each end of said stretch governing train movement in opposite directions into said stretch, code transmitting means including intermittently operated coding contacts normally acting to transmit driven code pulses over the track rails of each end track section toward the corresponding head-block signal, code sending means responsive to the cessation of driven code pulses normally received at each head-block signal to transmit reverse driven code pulses toward the other end of said stretch, and directional means for each head-block signal responsive to train movement into said stretch in the direction of traffic governed by that signal for preventing transmission of said reverse driven code pulses by said code sending means at the corresponding head-block signal, said directional means remaining effective until the normal driven code pulses have been restored in its respective end track section when that end track section becomes unoccupied.

38. In a coded track circuit signaling system for single track railroads, a stretch of single track between passing sidings and including an end track section at each end, a head-block signal at each end of said stretch for governing traffic into that stretch, code transmitting means including intermittently operated coding contacts and normally acting to transmit driven code pulses over the track rails of each end track section toward the corresponding head-block signal for causing that signal to indicate clear, and means responsive to the entrance of a train at either end of the stretch for rendering said code transmitting means for the end track section at the other end of said stretch ineffective to transmit driven code pulses and thereby put to stop the opposing head-block signal.

39. In a coded track circuit automatic block signaling system of the character described, the combination with a siding section of track adjacent the passing siding and stretches of single track extending in opposite directions therefrom, each of said single track stretches including an end track section adjacent the siding section, an entering signal at each end of said siding section and an intermediate signal in the rear thereof for governing train movement toward and into said siding section, code transmitting means for one particular end of said siding section normally acting to transmit driven code pulses over the track rails of said siding section, means responsive to the entrance of a train into the single track stretch associated with said particular end of said siding section for governing the rate of said driven code transmitted toward the opposing entering signal to cause its associated intermediate signal to indicate caution, means responsive to the movement of such train in said one single track stretch into the end track section thereof stopping transmission of all driven codes toward the opposing entering signal to cause that signal to indicate stop, and code transmitting means for the other end of said siding section rendered effective when the reception of driven

code pulses is thus stopped to transmit toward said particular end of said siding section, code pulses for governing the indications of the associated entering signal at a rate determined by the absence or presence and also the location of some train in the other single track stretch, said code transmitting means for the other end of said siding section providing a clear code rate if said other single track stretch is not occupied by a train approaching the siding, a caution code rate if that stretch is occupied by a train approaching the siding which has not advanced into the end track section of that stretch, and no code for stop control when such train has advanced into said end track section.

40. In a coded track circuit signaling system for governing the indications of entering signals and associated intermediate signals in the rear thereof governing train movement toward and into the siding section of track adjacent the passing siding by code pulses transmitted over the track rails and without line wires, code transmitting and receiving means for the opposite ends of said siding section, means responsive to the presence of a train approaching said siding section in one particular direction governing the code transmitting means for the associated end of said siding section to stop transmission of code pulses and put to stop an opposing entering signal and cause the opposing intermediate signal to indicate caution, means responsive to the approach of a train toward said siding section in the other direction for governing the rate of code pulses transmitted toward the opposing intermediate signal to cause its associated intermediate signal to indicate caution, and means responsive to the movement of such train approaching this siding section in said other direction past the corresponding intermediate signal for stopping transmission of all code pulses toward the opposing entering signal to put that signal to stop, said means also rendering the code transmitting means associated with said opposing entering signal effective to transmit code pulses for governing the indications of the entering signal for such train in accordance with the presence and location of a train approaching said siding section in the opposite direction.

41. In a coded track circuit system of automatic block signaling for single track railroads having a siding section of track adjacent a passing siding and stretches of single track extending in opposite directions therefrom, each of said single track stretches including an end track section adjacent said siding section, an entering signal at each end of said siding section and an intermediate signal in the rear thereof governing train movement toward and into said siding section, code transmitting means for the opposite ends of said siding section normally acting to transmit code pulses in opposite directions over the track rails of said siding section, means responsive to the entrance of a train into a particular one of said single track stretches at the end remote from the siding section for governing the code transmitting means for the corresponding particular end of said siding section to stop transmission of the normal code pulses toward the opposing entering signal, thereby causing that entering signal to indicate stop and its associated intermediate signal to give a double distant caution indication, means responsive to the entrance of a train into the other single track stretch at the end remote from the siding

section for governing the character of the code transmitted toward the opposing entering signal, thereby causing its associated intermediate signal to give a double distant caution indication, means responsive to the movement of such train in said other single track stretch into the end track section thereof for stopping transmission of all code pulses toward said particular end of said siding section and put to stop the opposing entering signal, said code transmitting means for said particular end of said siding section being rendered effective when reception of code pulses is thus stopped to provide code pulses for causing the entering signal at the other end of said siding section to give a clear or caution indication dependent upon the absence or presence of a train in said particular single track stretch unless such train has advanced into the end track section of that stretch.

42. In a coded track circuit system of automatic block signaling for single track railroads having a siding section of track adjacent the passing siding and stretches of single track extending in opposite directions therefrom, an entering signal at each end of said siding section governing train movement into that siding section, means for transmitting and receiving code pulses over the track rails of said siding section and single track stretches for governing the indications of said signals, said code transmitting means for the opposite ends of said siding section normally acting to transmit code pulses in both directions, means responsive to the entrance of a train into a particular one of said single track stretches at the end remote from the siding section for rendering the code transmitting means for the associated particular end of said siding section ineffective, and means responsive to the presence of a train in the other single track stretch approaching said siding only if within a limited distance thereof for stopping transmission of code pulses toward said particular end of the siding section, said code receiving means for said particular end of said siding section acting in response to such cessation of code pulses to change the control of the code pulses transmitted by the associated code transmitting means to provide a clear code if said particular single track stretch is not occupied or a caution code if that stretch is occupied by a train approaching the siding section until that train has come within a predetermined distance of the siding section.

43. In a coded track circuit signaling system for single track railroads having a siding section of track adjacent a passing siding and stretches of single track extending in opposite directions therefrom and each including an end track section adjacent said siding section, entering signals at opposite ends of said siding section governing train movement in opposite directions into said siding section, code transmitting means normally acting to transmit code pulses alternately in opposite directions over the track rails of said siding section, means effective when a train enters a particular one of said single track stretches at the end remote from said siding section for governing the rate of code pulses transmitted toward the opposing entering signal, means effective when such train has advanced into the end track section of said particular single track stretch for stopping all transmission of code pulses toward said opposing entering signal, and means associated with said opposing entering signal rendered effective by such cessation

5 of code pulses to transmit driven code pulses for governing the indications of the other entering signal in accordance with traffic conditions in the other single track stretch.

44. In a coded track circuit automatic block signaling system for single track railroads having a stretch of single track between passing sidings divided into a plurality of track sections, code transmitting means acting to transmit driven code pulses in one direction in each of said track sections, code transmitting means for the ends of said track sections receiving said driven code pulses, means responsive to the cessation of said driven code pulses in said one direction in each 10 track section for governing the operation of the associated code transmitting means to provide driven code pulses in the opposite direction, and directional means associated with the end of each track section receiving driven code pulses 15 in said one direction and energized by train movement in a direction to enter said track section at that end for rendering the associated code transmitting means ineffective until said driven code pulses transmitted in said one direction are again received at that end.

45. In a coded track circuit signaling system for railroads, an insulated track section, code transmitting means for the opposite ends of said track section normally acting to transmit code 20 pulses over the track rails of said track section alternately in opposite directions, means responsive to the cessation of code pulses received at one end of said track section for rendering the associated code transmitting means effective to transmit driven code pulses toward the other end at a rate in accordance with traffic conditions, and directional means governed by trains moving in the direction to enter said track section at said one end for preventing operation of 25 the associated code transmitting means while said track section is occupied by such train and until code pulses are again received at said one end.

46. In a coded track circuit signaling system for single track railroads, an insulated track section having signals at the opposite ends governing train movement in opposite directions into said track section, code transmitting means for each end of said track section operable at times to transmit driven code pulses over the track rails of said track section to govern the indications of the signal at the other end of said track section, directional means for one end of said track section energized by trains moving in a direction to enter said track section at that end and maintained energized while said track section is occupied by such train, and means acting while said directional means is energized to render ineffective code transmitting means for the corresponding end of said track section.

47. In a coded track circuit signaling system for railroads, a section of track, code transmitting means at one end of said section for normally applying a driven code to the rails of said section, a track relay at the opposite end of said section responsive to said normal driven code, decoding apparatus associated with said track relay and rendered active only so long as said track relay is operated in response to said normal driven code, a code sending relay having a pick-up circuit closed only momentarily when said decoding means is initially rendered inactive, a stick circuit for said code sending relay including its own front contact and a back contact of said track relay so that a single energization of said track relay releases said code sending relay, and

transmitting means for applying a reverse driven code when said code sending relay is picked up, whereby said reverse driven code is applied until said normal driven code is reapplied and momentarily energizes said track relay.

48. In a coded track circuit signaling system for single track railroads, the combination with the end track section of a stretch of single track at the end of a passing siding, a code transmitter relay and a code following track relay associated with the siding end of said track section, a code oscillator operating coding contacts at a predetermined rate, a code sending stick relay, an operating circuit for said code transmitter relay including said coding contacts and a front contact of said code sending relay and a back contact of said track relay, and a stick circuit for said code sending relay including a back contact of said track relay.

49. In a coded track circuit signal system for single track railroads, the combination with an end track section of a stretch of single track between the ends of passing sidings, a head block signal at the siding end of said track section for governing train movement into the stretch, an intermediate signal at the other end of said track section for governing train movement toward the siding, a code sending stick relay acting when energized to cause application to the siding end of said track section driven code pulses for governing indications of said intermediate signal, means for at times applying to the other end of said track section inverse code pulses during the off periods of said driven code, a code following track relay for the siding end of said track section, and stick circuit means for maintaining said code sending relay energized until said code following track relay is momentarily energized at a time other than during the off periods of said driven code.

50. In a coded track circuit signaling system for railroads, the combination with a track section, a source of current, a code following track relay, a code transmitter relay and coding contacts for intermittently connecting said source of current and said track relay alternately across the track rails of said section at one end at predetermined intervals to provide driven code pulses, means for at times applying to the track rails at the other end of the track section inverse code pulses during the off intervals of said driven code for intermittently energizing said track relay, a stick relay, and stick circuit means governed jointly by said coding contacts and by a back contact of said track relay for maintaining said stick relay energized while said track relay is energized by inverse code pulses and for releasing said stick relay when said track relay is

otherwise energized at the time said coding contacts are operated for the next driven code pulse.

51. In a coded track circuit signaling system for railroads, the combination with a track section, a source of current, a code following track relay, a code sending stick relay, a code transmitter relay and coding contacts effective only if said code sending relay is energized for intermittently connecting said source of current and 10 said track relay alternately across the track rails at one end of the track section to provide driven code pulses of a selected code rate, said transmitter relay being energized to apply a driven code pulse in response to operation of said coding contacts only if said track relay is deenergized at 15 that time, means for at times applying to the track rails at the other end of said track section inverse code pulses during the off intervals of the driven code, and stick circuit means governed 20 jointly by said coding contacts and by a back contact of said track relay for maintaining said code sending relay energized until said coding contacts are operated for the next driven code pulse at a time when said track relay is still energized, whereby said code sending relay is maintained energized in the presence of inverse code pulses but is automatically released by an energization of the track relay existing at the time when the next driven code pulse would be applied.

52. In a coded track circuit system for railroads, the combination with a track section, a source of current, a code following track relay, a transmitter relay acting when energized and de-energized respectively to connect said source of current and said track relay alternately across the track rails of the track section at one end, coding contacts for energizing said transmitting relay at predetermined intervals to provide driven code pulses, said code contacts being effective 40 when closed to energize said transmitter relay only if said track relay is deenergized at that time, means for at times applying inverse code pulses to the track rails at the other end of said section during the off intervals of the driven code, and a stick relay having two stick circuits, one of said stick circuits including a back contact of said track relay, and the other stick circuit being opened when said coding contacts are closed to energize the transmitter relay, whereby 45 said stick relay is maintained energized in spite of momentary energization of the track relay by inverse code pulses occurring during the off intervals of the driven code but is deenergized if the track relay is otherwise energized at a time 50 the coding contacts operate for the next driven code pulse.
